UNITED STATES PATENT OFFICE.

HARRY H. ADAMS AND CHARLES GORDON, OF CHICAGO, ILLINOIS, ASSIGNORS TO NATIONAL PNEUMATIC COMPANY, A CORPORATION OF WEST VIRGINIA.

VEHICLE.

Application filed September 11, 1922. Serial No. 587,405.

To all whom it may concern:

Be it known that we, HARRY H. ADAMS and CHARLES GORDON, citizens of the United States, residing at Chicago, in the county 5 of Cook and State of Illinois, have invented a new and useful Improvement in Vehicles, of which the following is a specification.

Our invention relates, more particularly, to passenger-carrying vehicles such as, for 10 example, street cars, busses and the like, and more especially to vehicles of the character stated employing one person only in their operation, such vehicles being commonly known as "one man control" vehicles.

Our primary object is to provide improvements in vehicles, especially of the "one man control" kind, to the end that the vehicle may be operated with a high degree 15 of safety and the boarding of passengers through the exit-way of the vehicle may be guarded against without requiring the attention of the operator. In this connection it is one of our objects to provide, as a part of the equipment of "one man control" cars as commonly provided, a separate exit-way, without requiring in the operation of the car the performing by the operator of material additional duties, and still render the vehicles operable with a 20 high degree of safety.

Without intending to be understood as enumerating all of the specific objects of our invention, certain of our specific objects are to provide a construction of car employing barrier means at the exit-way, which 25 may not be moved out of barrier-forming position by the act only of a passenger, but shall require in addition thereto an act by the operator of the car; to provide against the opening of the barrier means at the 30 exit-way until the operator has applied the brakes; to provide for the automatic return of the exit-way-barrier means to normal, closed, position upon the clearing of 35 the exit-way, and preferably also the exit-way step, of passengers regardless of any attention by the operator of the car; to provide for the automatic closing of the exit-way-barrier means when the brakes are 40 released, regardless of a passenger being in the exit-way; to afford selective control to the operator whereby he may condition the mechanism controlling the operation of the barrier means at the exit-door, so that the 45 passenger may effect the opening of the

barrier means, either in connection with the opening of barrier means at the entrance way, or independently thereof; to provide in a system involving barrier means at the exit-way controlled by a passenger, means whereby upon emergency application of brakes, the barrier means of both the entrance and exit-ways shall become balanced 50 permitting of the free passage of passengers through the ways; to provide, in a system involving brake-control mechanism, a control for the barrier means at the exit-way operable solely by the operator of the car, but only after the brake control mechanism 55 has been moved to brake-setting position, for effecting movement of the barrier means at the exit-way to open condition and preferably the return of the barrier means to normal position, this being especially desirable where the operator changes his station from one end to the other of a car at a terminal, permitting of the maintaining of the barrier means at the exit-way at 60 one end of the car in open condition, to permit of the alighting of passengers from the car, and the closing of these barrier means by the operator after he takes up his new station on the car at the opposite end; to provide novel, simple and positively-operating mechanisms for effecting the various 65 controls desirable to be provided; and many other objects as will be manifest from the following description.

Referring to the accompanying drawings: 70 Figure 1 is a view in side elevation of one end of a street car of a construction constituting one embodiment of our invention. Figure 2 is a plan sectional view of the structure shown in Fig. 1, the section being 75 taken on a plane above the center of the entrance and exit doors, these doors being shown by full lines in closed position and by dotted lines in open position, the steps adjacent to these doors being also shown by dotted lines in the position they occupy 80 when the doors are open. Figure 3 is a plan view of a portion of the under frame of the car shown in Fig. 1, together with portions of the mechanism located below 85 the plane of the platform, certain parts thereof being shown in section, this view showing by dotted lines the plate secured to the under-side of the platform to partially surround the opening therein in which 90 the treadle, forming a part of the construc- 95

tion, operates. Figure 4 is a broken, enlarged, section taken at the line 4 on Fig. 3 and viewed in the direction of the arrow. Figure 5 is a section taken at the line 5 on Fig. 3 and viewed in the direction of the arrow, this view showing a portion of the motorman's auxiliary-handle control. Figure 6 is a plan view of the treadle-equipped portion of the platform, with the treadle removed. Figure 7 is a bottom view of the treadle referred to, with certain portions broken away. Figure 8 is a bottom view of the plate, forming a part of the platform, and shown in dotted lines in Fig. 3, which 10 partially surrounds the opening in the platform in which the treadle operates, and to which the treadle is pivoted, portions of the treadle being shown by dotted lines. Figure 9 is an enlarged broken section taken 15 at the line 9 on Fig. 6 and viewed in the direction of the arrow. Figure 10 is a broken section taken at the line 10 on Fig. 9 and viewed in the direction of the arrow. Figure 11 is an enlarged section taken at 20 the line 11 on Fig. 6 and viewed in the direction of the arrow. Figure 12 is a broken section taken at the line 12 on Fig. 6 and viewed in the direction of the arrow. Figure 13 is an enlarged, broken section taken 25 at the line 13 on Fig. 3 and viewed in the direction of the arrow, illustrating mechanism by means of which the step, cooperating with the entrance door, is caused to be operated upon the act of actuating said door, the step being shown in uppermost position, the position it occupies when the entrance door is closed, certain of the parts through which the section line extends being 30 shown in elevation. Figure 14 is a view like Fig. 13 and of the parts therein shown, illustrating the position occupied by the step when swung to passenger-receiving position and when supporting a passenger, the entrance door, in this position of the step 35 being open. Figure 15 is a broken perspective view of a detail of the mechanism shown in Fig. 14. Figure 15^a is an enlarged broken section taken at the line 15^a on Figs. 1 and 3 and viewed in the direction of the 40 arrows. Figure 16 is a view in elevation of the intermediate portion of the mechanism shown in Fig. 5 and illustrating the manner of interlocking the motorman's auxiliary-control handle. Figure 17 is a section taken 45 at the line 17 on Fig. 16 and viewed in the direction of the arrow. Figure 18 is a view in side elevation of the mechanism shown in Fig. 16 with one part shown in section, the section being taken along the line 18 on Figs. 5 and 16 and viewed in the direction of the 50 arrows and another part shown partly broken away and in section. Figure 19 is a broken section taken at the line 19 on Figs. 2 and 3 and viewed in the direction of the 55 arrows. Figure 19^a is a section taken 60 partly at the line 19^a on Fig. 23 and partly at the line 20 on Fig. 23 and viewed in the direction of the arrows. Figure 20 is a section taken at the line 20 on Fig. 23 and viewed in the direction of the arrow. Figure 21 is a plan view of certain of the mechanisms shown in Fig. 19 with certain of the parts shown in plan section, the section being taken at the line 21 on Fig. 19 and viewed in the direction of the arrow. Figure 22 is a section taken at the line 22 on Fig. 19 and viewed in the direction of the arrow. Figure 23 is a plan section taken at the line 23 on Fig. 1 and viewed in the direction of the arrow. Figure 24 is a section 70 taken at the line 24 on Fig. 23 and viewed in the direction of the arrow. Figure 25 is a section taken at the line 25 on Fig. 23 and viewed in the direction of the arrow. Figure 26 is a plan sectional view showing the 80 motor for operating the exit door of the car, and a portion of the mechanism controlling the operation of this motor, the section being taken at the line 26—26 on Fig. 27 and viewed in the direction of the arrows. Figure 27 is a view in side elevation of the mechanism shown in Fig. 26 with certain of the parts in section, the section being taken at the irregular line 27—27 on Fig. 26 and viewed in the direction of the arrows. Figure 28 is a section taken at the lines 28 on Figs. 25 and 26 and viewed in the direction 85 of the arrows. Figure 29 is a section taken at the line 29 on Fig. 26 and viewed in the direction of the arrow. Figure 30 is a vertical sectional view of the mechanism controlling the supplying of fluid pressure to the exit-door-operating motor and the exhausting of the fluid pressure therefrom, this section being taken at the lines 30 on Figs. 100 26, 31, 32 and 33 and viewed in the direction of the arrows. Figure 31 is a section taken at the irregular line 31—31 on Fig. 30 and viewed in the direction of the arrows. Figure 32 is a view showing in plan certain of the parts shown in Fig. 30 and in section other parts thereof the section being taken at the line 32—32 on Fig. 30 and viewed in the direction of the arrows. Figure 33 is a 105 plan view of the port-equipped seat portion of the valve of the engine of Figs. 30 and 31, showing, by dotted lines, one of the positions occupied by the sliding port-equipped element thereof and cooperating with this seat. Figure 34 is a similar view with the slide portion of the valve omitted and showing, by dotted lines, the passages leading from the various ports shown. Figure 35 is a perspective view of a portion of the slide valve controlling the exit-door-actuating engine which valve cooperates with the ported seat portion shown in Figs. 33 and 34. Figure 36 is a view, in the nature of a 110 diagram, of the fluid pressure system through the medium of which the entrance 115 120 125 130

and exit-door-operating engines and the brake devices of the vehicle are operated, the system involving as a part thereof, a main controlling valve and its auxiliary-control valve above referred to for operation by the motorman. Figures 37, 38, 39 and 40 are views in the nature of diagrams of the controlling valve of Fig. 36, showing the ports by developed views, and only those ports which are effective in the several respective valve positions shown, Fig. 37 showing the positions occupied by the ports of the valve when the valve is in "release" position (Fig. 41), Fig. 38 showing the positions occupied by the ports of the valve when the valve is in the position indicated by the dotted line in Fig. 41 and entitled "Exit door open. Entrance door balanced. Brakes applied," Fig. 39 showing the position occupied by the ports of the valve when the valve is in the dotted position represented in Fig. 41 and entitled "Both doors open. Brakes applied," and Fig. 40 showing the position occupied by the ports when the valve is in the dotted line position represented in Fig. 41 and entitled "Emergency. Doors balanced." Figure 41 is a plan view of the stationary port-equipped portion of the valve. Figure 42 is a plan view of the rotatable port-equipped portion of the valve. Figure 43 is a bottom plan view of the valve member shown in Fig. 42. Figure 44 is a section taken at the line 44-44 on Fig. 42 and viewed in the direction of the arrows. Figure 45 is a view in longitudinal section of the emergency valve forming a part of the system shown in Fig. 36. Figure 46 is a plan sectional view of a modification of the construction forming the subject of the preceding figures, this view being taken above the entrance and exit-door-operating engines, and the mechanism cooperating therewith. Figure 47 is a broken view in side elevation of the portion of the mechanism shown at the right hand side of Fig. 46. Figure 48 is an enlarged broken section taken at the line 48 on Fig. 46 and viewed in the direction of the arrow. Figure 49 is a broken view in sectional elevation taken at the line 49 on Fig. 46 and viewed in the direction of the arrow. Figure 50 is a broken section taken at the line 50 on Fig. 49 and viewed in the direction of the arrow. Figure 51 is a broken plan section taken at the line 51 on Fig. 49 and viewed in the direction of the arrow. Figure 52 is a broken view, in sectional elevation, taken at the lines 52 on Figs. 46 and 53. Figure 53 is a plan view of a portion of the mechanism shown in Fig. 52. Figure 54 is a broken section taken at the line 54 on Fig. 52 and viewed in the direction of the arrow. Figure 55 is a broken section taken at the line 55-55 on Fig. 46 and viewed in the direction of the arrows, this view showing the exit-door-operating engine in sectional elevation. Figure 56 is a plan sectional view taken at the line 56-56 on Fig. 55 and viewed in the direction of the arrows, with the rotatable port-equipped portion of the valve and the cap therefor removed. Figure 57 is a section taken at the line 57 on Fig. 55 and viewed in the direction of the arrow. Figures 58 and 59 are plan views of the valve of Figs. 56 and 57 with the cover removed, these two figures showing the rotatable portion of the valve in its two extreme positions, Fig. 58 corresponding with the position occupied by the valve-operating member shown in Fig. 56. Figure 60 is a section taken at the line 60 on Fig. 56 and viewed in the direction of the arrow. Figure 61 is a broken section taken at the line 61 on Fig. 60 and viewed in the direction of the arrow, showing a portion of the valve-operating mechanism of Fig. 56. Figure 62 is a bottom plan view of the rotatable portion of the valve of Figs. 56 and 57. Figure 63 is a section taken at the irregular line 63-63 on Fig. 62 and viewed in the direction of the arrows. Figure 64 is a sectional view, in elevation, of the valve of Figs. 56 and 57, showing the ports by a developed view, the section being taken at the irregular line 64-64 on Fig. 58 and viewed in the direction of the arrows; and Figure 65, a diagrammatic view of the fluid pressure system through the medium of which the entrance and exit-door-operating engine of Figs. 46 to 64 inclusive, and the brake devices of the vehicle, are operated, the system involving as parts thereof the main and auxiliary control valves above referred to, for operation by the motorman.

Referring to the construction shown in Figs. 1 to 45 inclusive, the end platform of the car therein shown is represented at 75, it being shown as a continuation of, but slightly depressed below, the floor 76 of the body portion of the car, the front cross-seats of which are represented at 77 affording the aisle 78 therebetween. The car is shown as provided with a lengthwise-extending seat 79 at the closed side of the platform 75. The various stanchions at this end of the car, for supporting the adjacent side walls and roof, are represented at 80, 81, 82 and 83, the side of the car between the stanchions 81 and 82 presenting an opening through which the passengers board and leave the car, this opening being controlled by entrance and exit barriers shown as, and by preference, doors hereinafter referred to. The operator's seat is represented at 84, and it is so located as to render readily accessible for operation the motor-controlling mechanism represented at 85 and the main and auxiliary controlling elements 86 and 87, respectively, through the medium of which the brakes of the car are applied and

released and the operation of the entrance and exit doors controlled, all as hereinafter fully described. The platform 75 is provided with a rail 88 rising therefrom and preferably of the general curve form shown, this rail terminating at its depending end portion 89 preferably at a point on the car floor 76 closely adjacent to the platform 75 and substantially midway between the sides 10 of the platform, this rail thence extending toward the front end of the car and curving laterally toward the opening between the stanchions 81 and 82 adjacent to which its forward extremity 90 extends substantially midway between these stanchions and at which point it is connected with a hollow post 91 rising from the platform 75 and preferably connected at its upper end (not shown) with the upper structure of the car, 15 thereby defining on the platform 75 an entrance-way represented at 92 which extends adjacent the position of the operator's seat at 84, and an exit-way represented at 93, both of these ways opening at one end into 20 the interior of the car and at their other ends through the space between the stanchions 81 and 82.

The opening between the stanchions 81 and 82 is shown as provided with folding doors hereinbefore referred to and represented at 94 and 95, these doors meeting adjacent the post 91 and each being preferably formed of sections hinged together as shown. The door 94 is connected at one 25 edge with a vertically-extending shaft 96 located at the stanchion 82 and having journal support on the car in any desirable manner, as for example in accordance with common practice, the door 95 being connected 30 with a vertically-extending shaft 97 located adjacent the stanchion 81 and journaled to rotate, in any suitable way, as for example in accordance with common practice. The sections of the doors 94 are guided at 35 their upper ends in any suitable way, as for example as is common in constructions of this character, to cause these doors to assume the folded position represented by dotted lines in Fig. 2 when the shafts 96 and 40 97 are rotated in one direction, in which position the passengers may freely board and leave the car through the entrance and exit-ways 92 and 93, respectively, and to cause these doors to assume the full line position shown in this figure when the shafts 45 are rotated in the opposite direction. The platforms are also equipped with steps represented at 98 and 99 (Figs. 1 and 3), opposing the entrance and exit-ways 92 and 50 93, respectively, these steps being pivotally supported on horizontally-extending shafts as represented at 100 of the step 98 shown in Fig. 13. The shafts 100 are provided 55 with crank arms 101 the outer extremities 60 of which are pivotally connected with ends

of links 102 as represented at 103, the other ends of these links being pivotally connected at 104 to brackets 105 slidably engaging the guides 106 extending crosswise of the car. The brackets 105 are pivotally connected at 107 with the inner ends of links 108, the outer ends of which are pivotally connected as indicated at 109, with crank-arms 110 fixed on the lower ends of the door shafts 96 and 97, it being understood from the foregoing description that when the door shafts are rotated as hereinabove described to actuate the doors, the steps 98 and 99 will be simultaneously actuated, the arrangement of the parts being such that when the doors are closed the steps are in raised position (Fig. 13) and when the doors are open these steps are in passenger-receiving position. It may be here stated that the connection referred to between the step at the exit-door and the door shaft, as stated, is such that it will present slight lost motion, permitting of the depressing of the step a slight distance from the position to which it is moved in the opening of the exit door, by the weight of a passenger imposed thereon and operating against a spring device of a construction and for a purpose hereinabove described, with which the step engages when swung to passenger-receiving position. The rear portions of the steps are shown as provided with adjustable stop members in the form of nuts 111 and 111^a, respectively, which, when the steps are swung to laterally-extending position, extend directly in vertical alignment with rigid stop-surfaces 112 and 112^a provided as parts of the under-frame of the car, the entrance step abutting the stop 112 when the entrance door opens, and the member 111^a abutting the spring-device when the exit-door opens and before a passenger steps thereon.

Cooperating with the entrance-door shaft 96 is a compressed air-operated engine, represented generally at 113 (Figs. 23 and 36), which, in accordance with common practice, is formed of cylinders 114 and 115 in which separate pistons (not shown) operate (similar pistons, however, being shown in the exit-door engine of Figs. 26 and 27), and which are connected with a rock member 116 pivotally supported between its ends on a stationary part of the car, as represented at 117, the connections between the rock member and the pistons being represented at 118 and 119. Rigid with the rock member 116 is a gear segment 120 which meshes with a gear segment 121 rigid with the shaft 96, the engine, as stated, operating, when air is admitted to one end of the cylinder 114 which constitutes the so-called opening side of the engine, through the pipe 122, and the air in the cylinder 115 is permitted to exhaust therefrom through the pipe 123, the door-shaft 96 being rotated in counter-clock- 125 130

wise direction in Fig. 23 to move the entrance-door 94 to open position (the dotted position shown in Fig. 2), and when fluid pressure is supplied to the cylinder 115 through the pipe 123 and the cylinder 114 is free to exhaust through the pipe 122, the shaft 96 will be rotated in the opposite direction to close this door, the construction just referred to for operating the entrance door being of common and well known construction, it being understood that the operating mechanism just described is located in a plane above the entrance-door 94.

Cooperating with the exit-door-actuating shaft 97, and located above the plane of the latter, is mechanism for moving this door into and out of closed position. This is effected through the medium of a compressed air engine represented generally at 124 (Figs. 23, 26, 27, 28, 30 and 32), and, as in the case of the engine 113, being formed of two cylinders, represented at 125 and 126, in which pistons 127 and 128 operate, these pistons being connected through the medium of rods 129 and 130 with the ends of a rock member 131, these connections being pivotal as represented at 132 and 133. The rock member 131 is pivotally supported between its ends on a stationary part of the car, as represented at 134, and has rigid therewith a segmental gear 135 which meshes with a segmental gear 136 rigidly secured to the upper end of the exit-door shaft 97. The cylinder 125 constitutes the door-opening portion of the engine and the cylinder 126 the door-closing portion thereof, air being admitted to the ends of these cylinders and exhausted therefrom to effect the alternate operations of the pistons in these cylinders.

It may be here stated that the flow of fluid pressure to the entrance-door-operating engine 113 and the exhaust therefrom of the fluid pressure, is controlled wholly by the operator in manipulating the control lever 86. This, however, is not the case with the exit-door-operating engine 124. In the particular construction shown, wherein provision is made for the automatic return of the exit-door to closed position, upon the exit-way and the step 99 cooperating therewith being clear of passengers, the control of the flow of fluid pressure for operating the exit-door engine 124, to open the exit-door, requires not only the performance of an act by the operator but also is dependent upon a passenger being in the exit-way and upon an actuating device, shown as in the form of a treadle and hereinafter fully described; and the exhausting of the fluid pressure from the exit-door-operating engine 124 is dependent upon whether or not a passenger is on the treadle device or on the step, assuming that the lever 86 is in one of the "door opening positions" shown in Fig. 41. Assuming this position of the lever 86, the

exit-door closes, regardless of the position occupied by the entrance door, as soon as the treadle device and step 99 are clear of passengers.

The valve mechanism with which the exit-door-operating engine 124 is equipped for controlling the flow of fluid pressure to this engine and the exhausting of fluid pressure therefrom, and which is shown more particularly in Figs. 30 to 35 inclusive, comprises a stationary ported block portion 138 located beyond the cylinders 125 and 126 and containing the ports 139, 140, 141, 142, 143 and 144. The port 139 opens into the rear end of the door-closing side 126 of the exit-door-operating engine, and the port 140 opens into the rear end of the door-opening cylinder 125 of this engine. The ports 139 and 140 operate as initial exhaust ports, these ports opening into the respective cylinders 126 and 125 at points considerably in front of the positions to which the pistons move in their extreme inward movement in the cylinders in which they operate, as represented of the port 139 in Fig. 34. The port 141 leads to a muffler chamber 145 exhausting to the atmosphere at 146, this chamber being filled with any suitable muffling material as desired. The ports 142 and 143 are final exhaust ports, the port 142 opening into the rear end of the cylinder 126 and the port 143 into the rear end of the cylinder 125. The port 144 is an inlet port through which the fluid pressure for operating the engine and supplied from a pipe 147, is introduced. The various ports 139 to 143 inclusive terminate in the flat upper seat-surface of the member 138 and cooperate with a sliding valve member represented generally at 148 (Fig. 35), which slides upon the upper, seating, surface of the member 138. The bottom surface of the valve member 148 contains a T-shaped recess 149 (Fig. 35 which shows the member inverted), a relatively small port 150 which opens at one end through the under side of the valve member 148 and at its other end, through a side wall of the recess 149, and recesses, or cut-outs, 151 and 152 in the corners of the valve 148. The valve 148 is so guided in its movement, and its recesses 149, 151 and 152 are so positioned that when the valve occupies one of its extreme positions (Fig. 33), the port 140 will be open to the exhaust port 141 and the port 142 will be open to the inlet 144 through the cut-out 151, and the port 143 will be in communication with the recess 149 through the passage 150, thereby permitting fluid pressure to enter the cylinder 126 and exhaust from the cylinder 125 to operate the exit-door to closed position, the position shown in Figs. 26, 27 and 32; and when the valve member 148 is shifted to the right in Fig. 33 to its other extreme position, the port 130

139 will be open to the exhaust port 141 (closing the port 140 to the port 141), the port 143 will be open, through the cut-out 152, to the inlet port 144 (closing the port 142 to the port 144) and the port 142 will be open to the recess 149 through the passage 150, whereby fluid pressure is supplied to the cylinder 125 and exhausted from the cylinder 126 to effect the opening of the exit-door. It will be understood from the foregoing description that by reason of the relatively large initial exhaust ports opening into the cylinders between the ends of the latter and the several final exhaust ports, the initial movement of the pistons will be rapid, but greatly decelerated during the remainder of their movement, whereby a dash-pot action is produced preventing slamming of the door. The valve member 148 is shifted from one to the other of its extreme positions referred to, through the medium of a sliding member 153 provided at its opposite ends with cylindrical portions 154 and 155, the portion of the member 153 between these cylindrical portions being of reduced diameter and represented at 156 at which portion this member extends into a longitudinally-extending recess 157 in the block 148 between the shoulders 156^a on the member 153. The cylindrical portions 154 and 155 slide in cylinder portions 158 and 159 formed in a hollow valve-casing member 160 connected with the port-equipped member 138, as through the medium of the bolts 161. The member 153 cooperates with a coil spring 162 interposed between the piston 155 and the end wall of the cylinder in which it operates, this spring yieldingly forcing the member 153 to the left in Fig. 32 and holding it in a position in which the valve member 148 occupies the dotted position shown in Fig. 33 in which compressed air is supplied to the closing side 126 of the exit-door-operating engine. The cylinder portion 153 contains in its outer surface longitudinally-extending grooves 163 and by preference the piston portion 155 of the member 154 loosely fits the wall of the cylinder in which it operates, all for the purpose hereinafter described. The end wall of the cylinder 159 is ported as indicated at 164, this port opening into a chamber 165 communicating with a passage 166 leading to the atmosphere. The passage 166 is controlled by an inwardly-opening check valve 167 yieldingly held to its seat by a coil spring 168 located in the chamber 165, the outer end of the valve 167 extending beyond the valve casing as shown in Fig. 32, whereby it is operable as hereinafter described.

It will be understood from the foregoing description that in the normal position of the parts, viz., that shown in Figs. 26, 27 and 32, wherein the exit-door is closed,

the valve member 148 will occupy the position therein shown and shown by dotted lines in Fig. 33, as the air pressure within the valve casing and in the cylinder portions 158 and 159 is balanced. When, however, the check valve 167 is moved inwardly, the pressure between the piston portion 155 and the opposing end wall of the cylinder 159 rapidly reduces, with the result that the compressed air in passing through the grooves 163 and acting upon the end wall of the cylinder 158 opposing the piston portion 154, will force the member 154, together with the member 148, to the right in Fig. 32, to a position in which the member 148 opens the opening side 125 of the engine 124 to the supply of fluid pressure and exhausts the closing side thereof, these parts remaining in this position so long as the valve 167 is open. As soon, however, as the valve 167 closes, the member 153, together with the valve member 148, starts to move back to the position shown in Fig. 32 under the action of the spring 162, to return the valve member 148 to the dotted line position shown in Fig. 33 to open the closing side of the engine 124 to the source of fluid pressure and exhaust the opening side of this engine.

The actuation of the valve mechanism of Fig. 32, to effect the opening of the exit-door is accomplished, in the particular arrangement shown, in either of two ways, one by the act of the motorman in actuating the main control-lever 86 to either of the "door opening positions" shown in Fig. 41, combined with the presence of a passenger on the treadle device hereinbefore referred to and later described, which is located in the exit-way 93, these two conditions either being performed simultaneously or either one in advance of the other; or by the actuation, by the motorman, of the auxiliary control lever 87; a description of the mechanisms for thus operating the exit-door being as follows:

Journalized, and vertically movable, in a bearing 169 secured to the upper structure of the car at the platform portion thereof, and in a bracket 170 carried by the under frame of the car, is a shaft 171 shown as located within the post 91 extending from the platform 75 to the ceiling above the platform. The shaft 171 is provided adjacent its lower end with stops 173 and 174 shown as in the form of nuts screwed upon this shaft, these nuts being spaced apart. Cooperating with the shaft 171 at the stop portions 173 and 174 thereof, is a lever 175 rigidly secured at one end to a rock shaft 176 extending lengthwise of the car and journalized in bearing-brackets 177 depending from the under side of the platform 75, the outer free end of the lever 175 being bifurcated as represented at 178, at which

portion this lever straddles the shaft 171 between the stops 173 and 174 (Figs. 19 and 21). The shaft 176 is provided with a weighted arm 179 (Figs. 3 and 4) tending to rock this shaft in counterclockwise direction in Fig. 4 and in clockwise direction in Fig. 19. This shaft is also provided with arms 180 containing sockets 181 in their upper surfaces and extending to the side of the shaft opposite that beyond which the arm 179 extends (Figs. 3 and 4), this shaft being also provided with arms 182 which extend generally in the same direction as the arms 180. Cooperating with the shaft 176 at the arms 180 thereof, is a treadle device hereinbefore referred to as located in the platform 75 and represented at 183, this treadle device being located, and movable, in an opening 184 in the platform located in the exit-way 93, framed by a metal plate, represented at 185 and secured to the under side of the main portion of the platform 75. The side arm portions 186 of the plate 185 are provided, adjacent their ends, with inwardly-projecting lugs 187 adapted to form stops for limiting downward movement of the treadle 183, and the opposite end of the plate 185 is provided with depending brackets 188 to which the treadle is pivoted to adapt the latter to move up and down. By preference the treadle 183 is provided with arms 189 rigidly secured thereto at their outer ends, with their opposite ends extending inwardly beyond the opening 184 as shown in Fig. 4 at which portions they are pivoted to the brackets 188 by the pivoting means represented at 190. The treadle 183 is provided with depending studs 191 which seat at their lower ends upon the bottom surfaces of the sockets 181, it being understood from the foregoing that the weighted lever 179 tends to maintain the treadle 183 in raised position (Fig. 4) and that the weight of a passenger stepping upon the treadle 183 operates to depress this treadle with the result of rocking the shaft 176 in clockwise direction in Fig. 4, thereby swinging the lever 175 downwardly in Fig. 19 to engage the stop 174 on the shaft 171 with the result of lowering the latter. The arms 182 on the shaft 176 are provided for cooperation with levers 192 pivotally supported between their ends on brackets at the under side of the platform, as represented at 193. One end of each of the levers 192 is provided with an adjusting screw 194 which engages the upper surface of the adjacent one of the arms 182, the opposite end of each lever being pivotally connected, as indicated at 195, with the upper end of a vertically movable rod 196, these rods being guidingly supported on the under frame of the car (Fig. 4) in bearings 197 in the portion 112^a of the under

frame, the latter containing openings for these rods.

Coiled springs 199 surround the rods 196 and are confined between the bearings 197 and collars 200 rigidly secured to these rods, 70 these springs serving to yieldingly maintain the rods 196 and levers 192 cooperating therewith, in the position represented in Fig. 4 in which the collars 200 form stops cooperating with the parts 112^a, these 75 springs yieldingly resisting upward movement of the rods 196. The rods 196 are provided for cooperation with the step 99 at the exit-way, the lower ends of these rods projecting below the member 112^a and 80 engaging the upper surfaces of the nuts 111^a when the step 99 is swung to passenger-receiving position. In this connection it may be stated that the force exerted by the weighted lever 179 is sufficient to hold the 85 treadle 183 in raised position and together with the springs 199 is sufficient when no passenger is on the latter to hold the step 98 in slightly upwardly-inclined position 90 when no passenger is thereon, but insufficient to resist downward movement of the treadle 183 and the swinging of the step 98 to the position shown in dotted lines in Fig. 15^a when the weight of a passenger is imposed thereon. The upper end of the 95 shaft 171 is provided with annular flanges 201 and 202 vertically spaced apart and above these flanges with a crank-arm 203 (Figs. 19^a and 20), the portion of the shaft 171 between the flanges 201 and 202 extending through an elongated slot 204 in an arm 205 which is mounted on a shaft 208 and is free to revolve thereon except as limited by a pin 209 extending radially 100 from the shaft 208 into a circumferential 105 segmental slot 210 in the arm 205 (Fig. 20). The shaft 208 is journaled near the end thereof, opposite that carrying the arm 205, in a bearing block 211 (Figs. 26 and 29), this bearing block being provided with a pivot stud 212 at which it is journaled in a bracket 213 rigidly secured to the upper structure of the car, whereby the shaft 208 is capable of rotating and rocking about the axis of the pivot 212. This end portion of the shaft carries a finger 214 which projects upwardly and is adapted to cooperate with the stem of the reciprocating valve 167 of the exit-door-operating engine, upon actuating the shaft 208 as hereinafter described. The shaft 208 is also shown as provided with a collar 215 (Fig. 26) rigid thereon and having an eye 216 Figs. 26 and 28 to which one end of a coiled spring 217 (Fig. 28) is secured, the opposite end of this spring being rigidly secured to a stationary part of the upper structure of the car, this spring tending to rotate the shaft 208 in clockwise direction in Figs. 19^a, 20 and 29, the collar 215 being shown as provided with 110 115 120 125 130

an arm 218 having a lateral projection adapted to engage an opposing portion of the bracket 213 to limit rotation of the shaft 208 in the direction stated under the action of the spring 217. The shaft 208 adjacent the arm 205 is provided with a second arm 219 (Fig. 19^a) rotatable thereon except as limited by a pin 220 extending radially from the shaft 208 and into a segmental circumferential slot 221 in the arm 219, the outer end of the arm 219 being flexibly connected with the crank-arm 203 by the link represented at 222. The shaft 208 (Figs. 23 and 24) at a point intermediate the bearing 211 and the arm 205, is rotatably mounted in the substantially horizontally disposed arm 223 of a bell-crank lever 224 fulcrumed at 225 on a bracket portion 226 of a cylinder 231 secured to the stationary upper structure of the car. The depending arm 227 of the bell crank 224 is pivotally connected at 228 with the outer end of the stem 229 of a piston 230 located within the cylinder 231 and lengthwise movable therein, a coil spring 232 interposed between the piston 230 and the opposite end wall of the cylinder tending to hold the parts in the position shown in Fig. 24. The cylinder 231 contains a sleeve 223 surrounding the stem 229 and serving as a stop to limit outward movement of the piston 230 in the cylinder. The cylinder 231 is supplied, behind the piston 230, with fluid pressure, as hereinafter explained, flowing thereto through the pipe 234. The effect of actuating the piston 230 to move it to the right in Fig. 24, is to rock the shaft 208 upwardly at its right hand end in Fig. 23, about the axis of the pivot 212, and the various parts described are so proportioned and arranged, as shown, that, in order that the shaft 208 rotate in counter-clockwise direction in Fig. 25 sufficiently far to open the valve 167 it is necessary not only that the piston 230 be operated as stated but also that the shaft 171 be depressed to cause its flange 201 to be so positioned relative to the arm 205 that rotation of the shaft 208 to accomplish the purpose stated, will be effected. If a passenger steps upon the treadle 183 before air is admitted to the rear end of the cylinder 231 (Fig. 24) the rod 171 will be depressed and cause the flange 201 to become so positioned relative to the arm 205 that when fluid pressure is admitted to the cylinder 231 behind the piston 230 and the shaft 208 thereby tilted, as stated, the latter will rotate in counter-clockwise direction in Figs. 19^a and 20 sufficiently far to open the valve 167. In the event that the mechanism of Fig. 24 has been operated as stated, before the weight of a passenger becomes imposed on the treadle 183, the arm 205 will have been raised, by the tilting of the shaft 208 suffi-

ciently far so that the depressing of the rod 171 by a passenger stepping upon the treadle will cause the flange 201 to engage the arm 205 and rotate the shaft 208 to a position in which the valve 167 is opened. 70 As hereinbefore stated, the valve 167 of the exit-door-operating engine is also operable to open the door by the act of the motor-man in actuating the auxiliary control handle 87, a description of the mechanism through the medium of which this valve is operated being as follows: The control handle 87 is rigidly secured to the upper end of a vertically-disposed shaft 235 (Fig. 5) journaled at its upper end in a journaling member 236 secured to the front wall of the platform 75 and at its lower end in an opening 237 in the platform, this shaft projecting below the platform and carrying at its lower extremity a crank 238 (Figs. 3 and 5) 85 which is pivotally connected at 239 with one end of a rod 240, the opposite end of this rod being pivotally connected at 241 with a crank 242 rigidly secured to the lower end of the shaft 171, whereby when the shaft 90 235 is rotated through the medium of the handle 87, the shaft 171 is rotated and through the medium of the crank 203 and connecting element 222 the shaft 208 is rotated in counter-clockwise direction in Figs. 95 19^a and 20 sufficiently far to open the valve 167 of the exit-door-operating engine. The mechanism also comprises means resisting the movement of the control lever 87 as above stated and operating to return this lever and the parts connected therewith to normal position under the conditions hereinafter described, these means, as shown, comprising a coiled spring 243 surrounding the rod 240 and confined between a collar 105 244 thereon and a stationary block 245 in which the rod 240 slides.

In the particular mechanism shown the controlling lever 87 is releasably locked against actuation from normal position, until the control lever 86 is moved to a position in which the brakes are applied, and when the auxiliary controlling lever 87 is moved to exit-door-opening position it becomes automatically locked, and returns to 110 normal position, in which position the exit-door closes, upon the operator moving the lever 86 to a position in which the brakes are released. The shaft 235 (Figs. 16, 17 and 18) is provided with a sleeve 246 vertically slidable thereon, except as restrained by a pin 247 projecting radially from the shaft 235 and into a vertically elongated slot 248 in the sleeve 246, a coiled spring 249 surrounding the shaft 235 and being confined between the sleeve 246 and a recessed sleeve 250 rigidly secured to the shaft 235 above the sleeve 246, yieldingly forcing the latter downwardly to the normal position shown in these figures, the sleeve 246 being 125 130

provided with depending diametrically-opposed lugs 251. Located below the sleeve 246 and vertically slidable on the shaft 235 is a sleeve 252 containing in its upper edge 5 diametrically-opposed recesses 253 which, in the normal position of the parts referred to, extend at an angle of substantially 90° to the lugs 251 as shown in Figs. 16, 17 and 18. The sleeve 252 containing a recess 254 10 (Fig. 16) in its lower edge into which a pin 255 radiating from the shaft 235 extends in the normal position of the parts. The sleeve 252 is provided with a lateral arm-extension 256 having a depending stud 257 vertically 15 slidable in an opening 258 in a block 259 rigidly secured to the front wall of the platform 75, this block containing a chamber 260 forming a cylinder in which a piston 261 is vertically slidable, this piston being 20 secured to the lower end of a rod rigidly secured to and depending from the arm 256. A coiled spring 263 surrounding the rod 262 and confined between the piston 261 and an 25 end wall of the cylinder 260 yieldingly maintains the arm 256 with its sleeve portion 252 in the depressed position shown in Figs. 16 and 18 wherein the shaft 235 is locked 30 against rotation. The locking means just referred to are adapted to be raised to release the shaft 235 for rotation, by the introduction of fluid pressure into the lower end of the cylinder 260 for forcing the piston 261, together with the parts connected therewith, upwardly, against the action of 35 the spring 263, the fluid pressure for thus operating the piston being supplied from the source hereinafter described, through a pipe 264 opening into the lower end of the cylinder. It may be here stated that when the 40 sleeve 252 is raised, as stated, in which operation it forces the sleeve 246 upwardly against the tension of the spring 249, the shaft 235 is released for rotation and upon being rotated throughout an angle of approximately 45 90° , which opens the valve 167 of the exit-door-operating engine, the lugs 251 of the sleeve 246 spring downwardly into the recesses 253 under the action of the spring 249 and irreversibly lock the shaft 235 50 against return to normal position. When the fluid pressure is permitted to escape from the lower end of the cylinder 260 the spring 263 lowers the sleeve 252 thereby releasing the shaft 235 for rotation, the latter returning to normal position under the action of the spring 243.

Referring now to the fluid pressure mechanism controlled through the lever 86 for actuating the brakes of the car and 55 through the medium of which the entrance and exit-door-operating engines are operated (see Figs. 36 to 45 inclusive), this mechanism comprises a controlling valve represented generally at 265, an emergency valve 60 represented at 266, a main air reservoir

represented at 267, a brake-operating cylinder represented at 268 and the various connections hereinafter described. The valve 265, as to its general features of construction and general arrangement of all 70 of its ports except certain added ports, is the same as that commonly provided on street cars of the so-called safety type, and comprises the stationarily-supported, ported, disk-like member formed of the superposed 75 disk sections 269 and 270, a rotatable ported disk-like section 271 bearing against the upper face of the disk 270, and an inverted cup-shaped cover section 272 surrounding the disk 271. The disk 271 is adapted to be 80 rotated through the medium of the shaft 273 to the upper end of which the handle 85 86 is connected, the disk formed of the sections 269 and 270 containing ports 274 to 280 inclusive (Fig. 41). The port 274 opens into the port 275; the port 275 opens into a pipe 281; the port 276 opens into a pipe 282; the port 277 opens into a pipe 283; the port 278 opens into a port 284; the port 279 opens into a pipe 285; and the port 280 90 opens into the port 277 and consequently 95 communicates with the pipe 283 as shown diagrammatically, and by developed views, in Figs. 37 to 40 inclusive. The rotatable valve member 271 contains a chamber 286 95 provided with the ports 287 and 289 opening through the lower face of the member 271 and a port 290 opening from the chamber 286 to an arc-shaped port 288 on the lower face of the member 271. The member 271 also contains an arc-shaped port 100 105 292 on its under side, and a port 293 opening through its under side and opening through the upper side of the member at a restricted portion 294 of this port. The member 271 also contains the port 295 extending therethrough from its upper to its lower surface, and also contains a chamber 296 which is open to the upper side of the member 271 and 297 and to the under side 110 of this member at 296^a which is ported at 298 and 299, the port 299 being obliquely disposed as shown. The cover-section of the valve just referred to is provided with a port 270^a which opens at its upper end into the space provided by the member 272 and through which compressed air is constantly supplied as hereinafter described, the rotary member 271, located in this space, being thus subjected at all times to the fluid 115 pressure. The other end of the port 270^a 120 communicates with a pipe 270^b through the port 270^c disposed outside the circular section of the member 270 shown in Fig. 41. The various positions occupied by the control lever 86 in the positions to which it is 125 operated, are indicated by the dotted radial lines in Fig. 41 bearing legends indicating the conditions produced when this lever is moved to the indicated positions. 130

Referring now to the emergency valve 266 (Figs. 36 and 45), the construction shown is that commonly employed in street car installations of the general type above referred to, the valve comprising a casing 300 and affording the valve chamber 301 in which the differential piston device 302 is reciprocable, one end of the chamber 301, represented at 301^a, being of relatively small diameter as compared with the other end of this chamber, represented at 303. The portion of the piston which operates in the small end of the chamber 301 is represented at 304 and the portion of the piston 15 which operates in the portion 303 of the chamber is represented at 305. The intermediate portion of the piston structure 302 is of reduced diameter and presents the annular shoulders 306 spaced apart and between which a ported slide block 307 is mounted the port of which is represented at 308. The end of the chamber 301 adjacent the piston portion 304 is open to the atmosphere, as represented at 309, and the 20 opposite end of this chamber communicates with the pipe 282. The casing 300 contains a passage 311 opening at one end into the chamber 301 between the piston heads 304 and 305 and at its opposite end into a passage 25 communicating with a pipe 312, this pipe being also in communication with the chamber 301 at the other side of the piston head 305, through a passage 313 formed with a restriction 314. The casing 300 also 30 contains ports 315 and 316 located in the path of movement of the ported portion of the block 307, these ports communicating, respectively, with a pipe 317 and with the pipe 285.

40 Referring now to the diagrammatic showing in Fig. 36, the main air reservoir 267 opens into the pipe 312, this pipe being also connected with the pipe 270^b whereby the chamber in the cap 272 of the valve 45 (Fig. 38) is constantly in communication with the main air reservoir 267. The pipe 285 connects with the pipe 264 opening into the cylinder 260 of Fig. 18. The pipe 284 communicates with the pipes 122 and 234 at the coupling 318; the pipe 281 communicates with the pipe 123; the pipe 283 is an exhaust pipe and leads to atmosphere; and the pipe 317 which leads from the emergency valve (Fig. 45) opens into the 50 rear end of the brake cylinder 268.

The operation of the mechanism is as follows: The manipulation of the control lever 86 by the motorman to apply the brakes and open and close the entrance door 60 as desired, does not affect the position of the exit-doors, which remain closed in the various positions to which the lever 86 is operated, unless at the time this lever is moved beyond a given position a passenger 65 is on the treadle 183 or steps upon this treadle while the lever 86 is in the stated position. Assuming that a passenger is on the treadle 183, ready to alight from the car, the exit-door automatically opens upon the act of the motorman in rotating the lever 86 in counter-clockwise direction in Figs. 2 and 41 to cause it to occupy either one of the two dotted positions represented in Fig. 41 and bearing the legends "Exit-door open," etc., and "Both doors open," 70 etc., the exit-door remaining open until the passenger, or the last of a line of passengers leaving the car through the exit-way has cleared the exit-way and the step 75 99. The effect of depressing the treadle 183 is to rock the shaft 176 in clockwise direction in Fig. 4, with the result of rocking the lever 175 in counter-clockwise direction in Fig. 19, which depresses the rod 80 171 but not sufficiently to rotate the shaft 208, the annular shoulder 201 on the rod 171 in this operation, being moved downwardly into a position adjacent the upper surface of the arm 205. When the motorman rotates the handle 86 to either one of the two positions last above referred to, compressed air from the supply 267 enters the rear end of the cylinder 231 thereby 85 90 rocking the bell-crank 224 on its pivot 225 in counter-clockwise direction in Fig. 24, with the result of tilting the shaft 208 upwardly at its right hand end in Fig. 23. As the flange 201 extends closely adjacent to the arm 205 which rises with the shaft in 95 the tilting movement stated, this flange operates as an abutment restraining bodily upward movement of the arm 205, with the result that the shaft 208 rotates in counter-clockwise direction in Fig. 20, thereby 100 causing the finger 214 to engage the outer end of the inwardly opening check valve 167 and force the latter, against the action of the spring 168, to the left in Fig. 32 to 105 open the adjacent end of the cylinder portion 159 of the valve of this figure to the atmosphere. In the above-referred-to position of the lever 86, compressed air is supplied, through the pipe 147, to the valve chamber in which the valve block 148 is 110 located. Thus upon opening the valve 167 the air pressure against the member 153 operates to shift it to the right in Figs. 30 and 32, in opposition to the spring 162, into a position in which the air flowing into 115 this valve device is shut off from the cylinder 126 at the door-closing side of the engine and is admitted to the cylinder 125 at the door-opening side of the engine and the air in the cylinder 126 behind the piston 128 therein is permitted to exhaust, whereupon the exit-door opens to the dotted position represented in Fig. 2. It may be here stated that the normal position of the exit-door-operating engine, together 120 with its valve mechanism, is that illustrat- 125 130

ed in the drawings, in which position the valve block 148 is so positioned that the port 139 (Figs. 33 and 34), leading to the rear end of the cylinder 126, is open to the fluid pressure supplied to the valve chamber, and the ports 140 and 143 are open to the exhaust port 141. When the valve block 148 is shifted, by the air pressure, as above stated, this block slides to the right 5 in Fig. 32, thereby closing the port 142 to the interior of the valve chamber 160^a and opening the port 143 to this chamber, it being understood that the port 143 opens into the rear end of the cylinder 125 whereupon fluid pressure is supplied to this cylinder. The movement of the valve block 148, as stated, also closes the ports 140 and 143 to the exhaust port 141 and establishes communication of the ports 139 and 142, with the port 141, thereby permitting the air to exhaust from the cylinder 126 behind the piston therein. It will be noted that the ports 139 and 140 open into the respective cylinders 126 and 125 a considerable distance in front of their rear ends, whereby, in the operation of the mechanism as now being described, the piston 128 in moving to the right in Fig. 26 moves quite rapidly as the air in this cylinder exhausts through the relatively large passage 139, but as soon as the piston has closed this port, the operation of the engine is slowed down as the exhaust from this cylinder occurs through the port 142 which contains a constriction comprising the port 150 in the valve block 148. In other words, a relatively free venting of the cylinder in the initial return movement of the piston therein is afforded, but the remainder of its movement is rendered retarded by the air cushion afforded in the rear end of the cylinder, which prevents the slamming of the door to open condition. In the stepping of the passenger 40 from the treadle 183 to the step 99, the rod 171 remains in the raised position stated, according to the preferred arrangement of the parts and the normal movement of passengers in leaving the car, due to the weight imposed by the passengers upon the step which, through the engagement of the member 194 of the lever 192 with the arm 182, in opposition to the spring 199 and counterweighted lever 179, holds the shaft 176 45 in the position to which it was rotated by depressing the treadle 183, the arrangement, however, being such that the mere weight of the step when swung to passenger-receiving position is not sufficient to actuate the shaft 176 from the normal position illustrated to that in which the rod 171 is in lowered position. As soon as 50 both the treadle and step are clear, the parts through which the rod 171 was lowered, as stated, return, together with the shaft 171, to the normal position illustrated, thereby raising the flange 201, with the result that the shaft 208, while in tilted position, rotates, under the action of the springs 168 and 217, in clockwise direction in Fig. 30 with the result that the valve 167 is permitted to close under the action of the spring 168. The chamber 159 thus becoming closed to the atmosphere, the fluid pressure introduced into the valve casting of the exit-door-operating engine, enters the right hand end of the chamber 159 in Fig. 32 and as the pressure builds up in this part of the chamber the spring 162 becomes effective and finally forces the movable valve parts to the position shown in Fig. 32 in which condition of the valve the actuating fluid pressure enters the cylinder 126 behind the piston and establishes communication between the rear end of the cylinder 125 and the exhaust and the engine moves to the position shown in Fig. 26, its final movement being retarded, as explained in the door-opening movement of the engine, the operation of the engine, as stated, effecting the closing of the exit-door. It will thus be understood that in the operation of the device, as stated, while the opening of the exit-door requires a positive act on the part of the motorman in combination with an act of the passenger, which in the particular construction illustrated is involuntary, the closing of the exit-door is accomplished wholly independently of any act of the motorman, viz., by the act of the passenger alighting from the car, assuming that the motorman's control lever 86 remains in the position to which it is actuated as above described. It will be understood from the foregoing and the drawings that the above result of opening the exit-door will be accomplished even if the motorman should operate the control handle 86 to the given positions referred to before the passenger has stepped upon the treadle 183. Under such conditions the mechanism operating the exit-door-operating engine, instead of being operated as stated, viz., by first lowering the rod 171 by the action of the treadle device and then rocking the shaft in counter-clockwise direction in Fig. 20 by actuating the bell-crank 227 of Fig. 24, the bell-crank referred to would first be operated to tilt the shaft 208 which would raise the arm 205 (Fig. 20) to such a position that when the rod 171 is pulled down by a passenger stepping upon the treadle 183, the engagement of the shoulder 201 with the elevated arm 205 will operate to rotate the shaft 208 to a 110 position in which the valve 167 is opened. It may be here stated that, by reason of the parts in the valve controlled through the lever 86, the exit-door will move to closed position should the motorman operate the 120 125 130

control lever 86 toward release position beyond the given point referred to, viz, to the left beyond the dotted line in Fig. 41 bearing the legend "Exit door open," etc. as in such position the pipes 234 and 284 are opened to exhaust pipe 283 through the ports 278, 288, 290, 289 and 277.

Referring to the various pipe connections shown in Fig. 36 and the diagrammatic showing of the positions of the valve in Figs. 37, 38, 39 and 40: In the "release" position of the valve handle 86, represented in Fig. 41, the various ports of the valve controlled thereby, and which are effective in this position of the handle, are shown in Fig. 37 from which it will be noted that the interior of the valve casing is open to the fluid pressure in the main air reservoir 267, but is closed to all of the outlets from this valve; the pipe 147 is open to the air pressure in pipe 282 and the pipes 281 and 123 are also open to the air pressure in pipe 282 through the valve of Fig. 37, whereby air-pressure is maintained in cylinder 126 (Fig. 27) and cylinder 115 (Fig. 23) and the entrance and exit doors are held closed by air-pressure; and the pipes 284 and 285 are open to exhaust pipe 283. When the operator swings the lever 86 to the position designated "Exit door open," etc. (Fig. 41), the ports which become effective are those as indicated in Fig. 38. In this position of the valve the air-pressure from the main air reservoir 267 passes through the pipe 270^b and the passages 270^c and 270^a to the chamber 272^a and thence down through chamber 297 and ports 298 and 296^a through ports 278 and 279 respectively, and out through the pipes 284 and 285, respectively, 40 through which it flows through the pipe 284 to pipes 234 and 122 and thence into the rear end of the cylinder 231 to actuate the bell-crank-lever 227 as hereinbefore described and from the pipe 122 into the door-opening side 45 114 of the entrance-door-operating engine 113, which latter becomes balanced without operating the entrance door, as the opposite side of this engine is still open to the air supply through pipe 312 and the emergency valve 266 through ports 314 and 313 (Fig. 45) and thence through pipe 282 and ports 276, 292, 274 and 275 and pipe 281—123, it being noted that before the engine 113 may 50 operate, the closing-side of this engine must be vented through the pipe 281 to the pipe 283 and thence to atmosphere. In this position of the valve the exit-door is operated provided the treadle becomes depressed, as hereinbefore stated. In this position of the 55 valve controlled by the handle 86, fluid-pressure also passes from the main air reservoir 267 through the pipe 285, the port of the movable slide valve 307 of the emergency valve 300 (Fig. 45) and thence out through 60 the pipe 317 to the brake cylinder for oper-

ating the brakes of the car, air also passing through the pipe 264 and into the lower end of the cylinder 260 to elevate the locking means 256 controlling the auxiliary control lever 87, the purpose of which (Fig. 18) is hereinafter fully explained. In the further rotation of the control lever 86 to the position designated "Both doors open" (Fig. 41), such of the ports of the valve controlled by the lever 86 as become effective in this position of the valve are represented in Fig. 39, the only change which results in the pipe connections in moving the lever to this position being that the pipe 281 becomes closed to the pipe 282 and open, through the ports 274—275, 292, 280 and 277, to the exhaust pipe 283, in which position of the valve the cylinder 115 of the entrance-door-operating engine 113 is allowed to exhaust, and as air is being supplied to the opposite side of the engine through the pipe 122 the entrance door 94 is swung to open position. When the control lever 86 is moved back toward "release" position beyond the position designated "Exit door open," etc. (Fig. 41) the pipe 281 is caused to communicate with the charged pipe 282, the pipes 234 and 122 are vented to atmosphere through pipes 284 and 283 and the cylinder 126 is opened to the pressure supply, whereupon both the entrance and exit doors close and are held closed by the fluid pressure.

It will be observed from the foregoing that the supply of air from the main air reservoir 267 to the various operating parts is through the valve of which the lever 86 is a part. The emergency valve of Fig. 45 is provided, in accordance with common practice, to by-pass, under the control of the operator, the air to the brake cylinder 268 so that the latter may be caused to operate more quickly than if the air for operating was required to be passed through the motorman's valve. In devising my improved system I have provided for the use of an emergency valve for the general purpose commonly provided associating such a valve with the door-engine-operating and controlling devices so that in the case of an emergency application of the brakes, both the entrance and exit doors will be balanced permitting passengers to readily leave the car through either or both the exit and entrance ways by merely pushing the doors open as they pass through these ways.

It will be observed from Figs. 37, 38 and 39 that in the positions of the valve controlled by the lever 86, and corresponding with certain of the positions shown in Fig. 41 and hereinbefore referred to, the pipe 282 is never open to the atmosphere, but always contains the main air reservoir pressure. Therefore the pressure of the air against the differential portions 304 and 305 of the

valve-operating piston device of Fig 45, is equalized whereby the latter remains at all times in the position shown in Fig. 45. When, however, the operator moves the lever 86 to the position designated "Emergency" (Fig. 41), the pipe 282 is open to the exhaust pipe 283 (Fig. 40) through the medium of the ports 276 and 287, through the chamber 286 and the ports 289 and 277 with the result that the end of the cylinder 303 to the right in Fig. 45 of the piston head 305 therein, becomes quickly exhausted of the air pressure therein and as the passage 313 contains the restriction 314 preventing the quick building up of pressure in this part of the cylinder, the piston device 302 shifts to the right in Fig. 45, thereby opening the port 315 to the chamber 301^a and consequently to the main air reservoir pressure through the pipe 312, whereupon the brake cylinder 268 is supplied directly from the emergency valve with air pressure for actuating the brakes. The emergency positioning of the valve, as stated, results in the balancing of both the entrance and exit doors, to permit the passengers to push them open, as stated, by reason of the opening of the pipes 281, 282 and 284 to the exhaust pipe 283, whereby no air pressure is supplied to either the exit-door-opening engine or the entrance-door-opening engine, and the cylinder 126 of the exit-door-opening engine and the cylinders of the entrance-door-engine, are opened to the atmosphere, as stated.

It will be observed that in the position of the valve shown in Fig. 40, there is no passage of the air from the main air reservoir 267 through this valve.

Upon the return of the control lever 86 to "release" position (Fig. 41), in which position the pipe 282 is closed to the exhaust 283 and is connected through the ports 294 and 293 to the reservoir pressure which is maintained in chamber 272^a through pipe 270^b the pressure behind the piston portion 305 builds up and effects the return of the valve to the position shown in Fig. 45.

It will be noted that the operation of the exit-door to open position is dependent, in so far as the control thereof through the lever 86 is concerned, upon the movement of this lever to, or beyond, the position designated "Exit door open," etc. (Fig. 41), and consequently, upon the brakes being applied; and the closing of the exit-door will occur even though a passenger is on the treadle 183, in the event of the motorman rotating the lever 86 reversely to extend to the left of the position designated "Exit door open," etc. in Fig. 41, as by such movement of the lever 86 the pipe 284 becomes closed to the main air reservoir 267.

Provision is made in the particular construction now being described for accomplishing the opening of the exit-door 95 solely by an act of the operator of the car. This is accomplished through the auxiliary mechanism 87 (Figs. 2, 5, 16, 17 and 18) hereinbefore described. The opening of the pipe 285 to the air pressure from the reservoir 267 in the position of the valve 265 of Fig. 36 for applying the brakes on the car as described, supplies air pressure through the pipe 264 to the cylinder 260 (Fig. 18) whereupon the member 256 rises against the action of the spring 263, disengaging this member from the pin 255. The shaft 235 is then free to be rotated by the operator throughout, in the particular construction shown, substantially 90°, in which position the member 256 becomes interlocked at its recesses 253 with the depending lugs 251 on the collar 246 and holds this shaft against return movement until the supplying of air to the cylinder 260 ceases. In rotating the shaft 235 it is swung in counter-clockwise direction in Fig. 3, with the result of rotating the rod 171 (Figs. 19, 19^a, 20 and 22) in clockwise direction in Fig. 3 which rocks the arm 221 in counter-clockwise direction in Fig. 19^a with the result that the shaft 208 is rotated sufficiently to open the valve 167 of the exit-door-operating engine, whereupon this engine operates to open the exit-door 95 as hereinbefore explained. Having actuated the shaft 235, as stated, this shaft, together with the parts operated thereby as stated, remains in the position to which it was moved, until the control lever 86 has been returned to a position in which the brakes are released, whereupon the shaft 235 automatically returns to normal position under the action of the spring 243 and the valve 167 is thus permitted to automatically close, whereupon the exit-door-operating engine automatically closes the exit-door as hereinbefore explained.

It may be here stated that the feature of locking the exit-door open as just explained, is of particular advantage where the car is equipped at opposite ends with entrance and exit doors and operating mechanism therefor, as explained, as it permits the motorman in changing his position from one end of the car to the other end to leave open the exit-door at the platform he vacates, to permit passengers to freely leave the car, and return this exit-door to closed condition upon actuating the brake-valve, like that controlled by the lever 86, at the opposite end of the car, to "release" position, it being understood that the member 256 (Fig. 18) is returned to the normal, lowered, position shown in this figure upon discontinuing the supply of air pressure to the brake cylinder 268 through the pipe 285, it being noted from Fig. 37 that in the "release" position of the handle 86 (Fig. 41) the pipe 285 communicates with the exhaust pipe 283 through the medium of the ports 279 and

287, through the chamber 286, and the ports 289 and 277 (Figs. 37, 41 and 43). In the embodiment of the invention illustrated in Figs. 46 to 64 inclusive, the car platform would be provided with the entrance and exit ways and doors and steps therefor as explained of the construction of the preceding figures and also controlling elements, which may be the elements 86 and 87 hereinbefore described. In this construction, disregarding for the moment the control through the auxiliary handle 87, the opening of the exit-door requires movement of the handle 86 to the position designated "Both doors open," etc. (Fig. 41), and the act of the passenger in stepping upon the treadle located in the exit-way, these acts occurring either simultaneously or one in advance of the other, and the closing of the exit-door is effected by the passenger leaving the exit-way and step co-operating therewith. In this connection it may be stated that inasmuch as the exit-door, in the manipulating of the element 86, is not opened independently of the entrance door, the valve controlled by element 86 need not provide for the positioning of the valve designated "Exit door open. Entrance door balanced" in Fig. 41. In fact the valve controlled by the handle 86 may be the standard safety valve commonly used on safety cars. The exit-door is also operable by the motorman through the medium of the auxiliary handle 87, after the latter is unlocked by the movement of the handle 86 to a position in which the brakes are applied, and while the passenger is on the treadle, independently of the opening of the entrance door, the exit-door remaining open as long as a passenger is on the treadle or on the step at the exit-door, the auxiliary handle 87 being held by the motorman in a position to effect the operation just stated, and upon the motorman releasing his grasp of the handle the latter returns to normal position and the exit-door closes. The exit-door may also be opened by the motorman regardless of the opening or closing of the entrance door, and independently of a passenger being on the treadle, by operating the auxiliary handle 87, in which position this handle becomes locked and returns to normal position, the exit-door also returning to closed position, upon the releasing of the brakes of the car by manipulating the handle 86 provided no passenger is on the treadle or the step at the exit-way.

In the modified construction referred to the entrance door shaft, represented at 319, carries a crank-arm 320 pivotally connected at 321 with a bent link 322 pivotally connected at 323 with one end of a cross-arm 324 connected between its ends with a shaft 325 forming a part of the entrance-door-op-

erating engine 326 which in the structure shown is of common construction, the shaft 325 being rocked in clockwise direction in Fig. 47 to open the entrance door when fluid pressure is admitted to the right hand end of the cylinder represented at 327 and exhausted from its opposite end and rocked in counter-clockwise direction in this figure when fluid pressure is admitted to the left hand end of the cylinder 327 in Fig. 47 and exhausted from its opposite end. The outer ends of the cylinders 327 and 328 communicate with pipes 334 and 335, respectively, through which the fluid pressure is alternately admitted into the cylinders and exhausted therefrom, as hereinafter described. The cross-arm 324 at the end thereof opposite that to which the link 322 is pivoted is pivotally connected, as represented at 336, with one end of a bent lever 337, the opposite end of which carries a cross-pin 338 mounted to move in a direction crosswise thereof, in guides formed of the upper members of a frame 339 rigidly secured to the upper structure of the car above the entrance and exit-doors, and strap members 340 secured to this frame member. The pin 338 forms a pivotal support for a bell-crank-lever 341, this pin extending through the bell-crank at the angle portion of the latter, the arm 342 of this bell-crank lever being provided at its extremity with a roller 343 for a purpose hereinafter described. The upper member of the frame 339 is slotted lengthwise thereof, as indicated at 344 (Fig. 52) to adapt this bell-crank to rock when operated as hereinafter described. The upwardly-extending arm 345 of the bell-crank 341 is pivotally engaged at 346 to one end of a link 347 the opposite end of this link being pivotally connected, as represented at 348, to a lever 349 fixed at its end on a shaft 350 journaled in upwardly-extending brackets 351 secured to the upper structure of the car. One extremity of the shaft 350 carries a downwardly-extending lever 352 rigidly secured thereto and co-operating with the valve mechanism hereinafter referred to. The shaft 350 towards its opposite end has rigidly secured thereto an arm 353 to the outer end of which the upper end of a vertically-extending rod 354 is pivotally connected, as indicated at 355. The rod 354 extends downwardly through a vertically-movable sleeve 356, these parts being both vertically movable and relative to each other, and located within a stationary pipe housing 357 and corresponding with the housing 172 of the preceding figures. The lower end of the rod 354 is pivotally connected, as indicated at 358, with the outer end of a lever 359 corresponding with the lever 175 of the preceding figures and operated from the treadle device in the exit-way, in the same manner, this lever rocking downwardly, to

depress the rod 354 when a passenger steps upon the treadle. The rod 354 is provided toward its upper and lower ends with flanges 360 and 361, respectively, for a purpose hereinafter described.

The mechanism just described is provided for the purpose of controlling the so positioning of the valve of the exit-door-operating engine hereinafter referred to, that the 16 exit-door will be moved to open position, this being effected by rotating the shaft 350 in clockwise direction in Fig. 47, by the depressing of the rod 354. Provision, however, is made for locking rod 354 against lowering 15 when a passenger steps upon the treadle in the exit-way, until, according to one method of operating the structure, the entrance-door engine is operated to open the entrance door, or, in accordance with another 20 method of operation, until the motorman's auxiliary handle 86 is operated. The locking mechanism referred to comprises a bolt 362 (Fig. 52) horizontally slideable between pins 363 and 364 mounted in a 25 bracket 365 on the frame 339, this bolt having a stem 366 which slides through an opening 367 in the rear wall of this bracket, a coil spring 368 surrounding the stem and confined between a wall of the bracket 365 and the opposing surface of the bolt 362 operating to yieldingly maintain this bolt in the projected position shown in Fig. 52, the 30 stem 366 being provided at its outer end with a clip 369 having ears spaced apart, one of 35 which is represented at 370, and containing elongated slots as shown of the one ear at 371. A pin 372 extends loosely through these slots and affords a pivotal connection between the clip 369 and one end of a link 40 373, the opposite end of this link being pivotally connected, as represented at 374, to an arm 375 of a bell-crank-lever 376 pivotally supported at its angle portion, as represented at 377, on a bracket 378 secured to the 45 frame 339, the outer end of the other arm 379 of this lever being pivotally connected, as indicated at 380, to the upper end of a link 381, the lower end of which is pivotally connected, as represented at 382, to a head 383 rigidly secured to the upper end of the tube 356, there being confined between this head 383 and the upper end of the pipe 357, a coil 50 spring 384 which surrounds the tube 356 and operates to yieldingly hold the latter in raised position (Fig. 49).

The arrangement of the parts above described is such, as shown in Figs. 46, 47, 49, 50, 52 and 53, that in the normal positions thereof, in which the entrance and exit doors are closed, the bolt 362 extends immediately above the roller 343, thereby obstructing rotary movement of the lever 341 on the pivot 338 and thus should a passenger step on the treadle while the entrance-door-operating engine is in the posi-

tion shown in the drawings, the treadle will remain in raised, normal, position by reason of the abutment afforded by the bolt 362. The operation of the entrance door engine to open the entrance door, the shaft 325 rotating in clockwise direction in Fig. 48 in this operation, slides the bell-crank 341 along the guide-ways 340 to a position in which the roller 343 is withdrawn from position beneath the bolt 362, thereby permitting 70 this bell-crank to rock under the weight of a passenger on the treadle, whether the passenger has stepped onto the treadle before the entrance-door-operating engine has been operated, as stated, or after 75 this engine has operated.

As before stated, the bolt 362 is also adapted to be retracted to clear the bell-crank 341 by depressing the tube 356 to release the lever 341 for clockwise movement 80 in Fig. 47 upon the lowering of the rod 354 which is effected either by the presence of a passenger on the treadle in the exit-way, or by the lowering of the tube 356, as herein-after described, by the operation of the motorman's auxiliary lever 87, to a position in which a flange 385 engages the shoulder 361 and forces the latter, and with it the rod 354, downwardly sufficiently far to actuate 85 the shaft 350 to the same extent as in the case of a passenger stepping upon the treadle.

In this connection it may be stated that the tube 356 is provided with laterally-extending ears 386 between which the upper end of a link 387 is pivoted as indicated at 388, the lower end of this link being pivotally connected, as indicated at 389, to one arm 390 of a bell-crank-lever 391 fulcrumed at 392 to depending brackets 393 on the car platform, the lower end of the other arm 394 of this bell-crank being pivotally connected, as represented at 395, to a rod 396 corresponding with the rod 240 of Fig. 3 and connected with the motorman's auxiliary handle 87 as explained of the rod 240 in the previously described construction, it being understood that when the motorman actuates the auxiliary handle 87 in counter-clockwise direction in Fig. 32, the tube 356 will be depressed. The parts of the structure are preferably so arranged that in the rotation of the handle 87 as stated to a position intermediate the normal position represented in Fig. 17, and a position in which the member 256 interlocks at its recess 253 with the lugs 251 on the operating shaft 235, the tube 356 will be lowered sufficiently to withdraw the bolt 362 from the lever-obstructing 100 position shown in Fig. 52, but will not depress the rod 354, but upon rotating the auxiliary handle 87 to a position in which the lugs 251 enter the recesses 253, in which 105 position the auxiliary handle becomes 110 locked, the tube 356 will become depressed 115 120 125 130

sufficiently to force the rod 354 downwardly to a position in which the shaft 350 is rotated to an extent sufficient to cause the valve mechanism of the exit-door-operating engine to be in a position for supplying fluid pressure to this engine for opening the exit-door. The exit-door-operating engine, represented generally at 397, and hereinbefore referred to, is of the same general type as the entrance-door-operating engine and involves a cylinder 398 in which a double-headed piston, the heads of which are represented at 399 and 400, is located and longitudinally movable. The stem connecting the heads 399 and 400 is represented at 401, this stem being provided with a rack portion 402 meshing with a gear segment 403 secured to a shaft 404 mounted in the casting of the engine, the outer end of this shaft carrying a crank arm 405 pivotally connected at 406 with one end of an arm 407, the opposite end of which is pivotally connected at 408 with a crank 409 secured to the upper end of the exit-door shaft 410 and corresponding with the shaft 97 of the preceding figures, it being understood that upon shifting the piston of this engine to the right in Fig. 56, the exit-door will open and upon returning it to the normal position shown in this figure, the exit-door will close. The engine referred to is provided with an oscillating valve, represented generally at 411, adapted in its oscillations to alternately direct fluid pressure supplied to it as hereinafter described, into the opposite ends of the cylinder 398 and exhaust the fluid pressure therefrom to cause the piston device to operate as stated, the rotary portion of this valve, and represented at 412, being fixed to the upper end of a shaft journaled in the body portion of the valve and provided at its lower end with an arm 413 carrying a pin 414 which extends through and is slidably in a slot 415 provided in a slide bar 416 pivotally connected at its other end, as indicated at 417, with a stem 418 of a dash-pot 419 rigidly secured to the upper structure of the car and operating in conjunction with slot and pin connection 414—415 to present the desired delay in the beginning of the movement of the door to closed position. The bar 416 contains, between its ends, an elongated slot 420 into which the lower end of the lever 352 extends and through the medium of which latter this bar is shifted to the left in Fig. 46 to rotate the valve, the movement of the bar 416 and the valve to normal position being effected through the medium of the spring 419.

The rotatable valve member 412 cooperates with the stationary body portion of the valve hereinbefore referred to and represented at 421, which carries a cup-shaped cover portion 422 spaced from the top sur-

face of the valve member 412. The stationary body portion of the valve 421 contains six ports, 423 to 428 inclusive, which open through the upper surface of this member and are grouped about the center thereof as shown. The port 423, which is an exhaust port, opens into the cylinder 398 substantially midway between the ends of the latter, the opposing wall of the cylinder being formed with an exhaust port to the atmosphere, represented at 429. The port 424 communicates with a passage 430 which opens into the cylinder 398 at a point between the extreme positions to which the piston 400 is moved in its reciprocations, this port and passage forming an exhaust for this end of the cylinder. The port 425 communicates with a passage 431 which opens into the extreme left hand end of the cylinder 398 in Fig. 56, this port and passage being alternately an inlet and exhaust. The port 426 is an inlet port and communicates with the pipe 432 through which fluid pressure is constantly supplied to the port 426. The port 427 communicates with a passage 433 which opens into the extreme right hand end of the cylinder 398 in Fig. 56 and serves alternately as an inlet and an exhaust for this end of the cylinder; and the port 428 communicates with a passage 434 which opens into the cylinder 398 between the two extreme positions occupied by the piston 399 in its reciprocations, this port and passage constituting an exhaust. The rotatable member 412 contains an arc-shaped opening 435 extending entirely therethrough and adapted to alternately effect communication between the inlet port 426 and the ports 425 and 427, the two positions occupied by this valve being represented in Figs. 58 and 59. The under side of the valve member 412 contains a recess of irregular shape and represented at 436, a portion of this recess being located at the axis about which the member 412 rotates, this member also containing the ports 437 and 438 which open through the bottom surface of the member 412 and, through laterally-extending branches 439 and 440, open into the recess 436.

The arrangement of the various ports and passages in the parts of the valve 411 are such that in the normal position of the apparatus, viz., that shown in Figs. 56, 57, 58 and 60 to 64 inclusive, the passage 436 is in registration with the exhaust port 423 and the port 424 and also, through the port 437, in registration with port 425. In this position of the valve the fluid pressure supplied to the pipe 432 enters the right hand end of the cylinder 398 to actuate the piston to the left in Fig. 56, to the position therein shown, the air in the opposite end of the cylinder 398 exhausting through the passage 430, and ports 424, 423 and 429 to the at-

mosphere. When the valve-actuating rod 416 is shifted to the left in Figs. 46, 47 and 56, as hereinbefore described, the rotatable member 412 of the valve 411 is rotated in 5 clockwise direction in Fig. 56 to the dotted line position represented at 441. This results in moving the port 435 in the valve out of registration with the port 427 and into registration with the port 425, and 10 moves the recess 436 out of registration with the port 424 into registration with the port 428; moves the port 437 out of registration with the port 425, and the port 438 into registration with the port 427. In this position 15 of the valve the fluid pressure supplied from the pipe 432 enters the left hand end of the cylinder 398 in Fig. 56, and the compressed air previously introduced into the right hand end of the cylinder 398 is permitted 20 to exhaust through the passages 433 and 434 to the atmosphere. The piston device 399—400, thereupon moves to the right in Fig. 56, with the result of opening the exit-door, which latter remains open so long as 25 the valve 411 remains in the position stated. Upon returning the bar 416 to normal position (Fig. 56), the valve 411 is returned to normal position shown in this figure, whereupon the actuating fluid pressure enters the 30 right hand end of the cylinder in Fig. 56 and exhausts from the opposite end, with the result of effecting the closing of the exit-door.

It will be noted that as to both ends of 35 the cylinder 398, provision is made for relatively great freedom of exhaust from the end of the cylinder opposite that into which the actuating pressure is introduced, during the initial movement of the piston, the exhaust occurring through both of the passages leading into the end portion of the cylinder, but before the piston has reached the limit of its stroke one of the exhaust 40 passages closes, leaving the one at the extreme end of the cylinder the only one 45 through which exhaust may occur and this only through a retracted port, the port 437—438, as the case may be, and thus slamming of the doors is prevented.

It is contemplated that the mechanism of 50 Figs. 46 to 64 inclusive be incorporated with other apparatus for controlling the supplying of fluid pressure thereto as for example, and by way of illustration, the apparatus shown in Fig. 65, those parts thereof which correspond with the parts shown in Fig. 36 being given similar designating numerals. In this arrangement the pipe 334 communicates with the pipe 284; the pipe 335 communicates with the pipe 281; the pipe 335 communicates with the pipe 281 (the pipe 234 of Fig. 36 being omitted); and the pipe 432 communicates with pipe 282. When the motorman moves the lever 86 to the "Both doors open," etc., position 55 (Fig. 41) or to the right in this figure beyond this position, compressed air flows from the tank 267 through the valve controlled by the lever 86 and pipe 284 and pipe 334 into the right hand end of the cylinder 327 in Fig. 47, with the result of 60 rocking the shaft 325 in clockwise direction in this figure and withdrawing the bell crank 341 from the position therein shown into the dotted line position represented in 65 this figure. If a passenger is on the treadle in the exit-way at the time the motorman actuates the lever 86 as stated, the valve 412 controlling the exit-door-operating engine will be moved by the weight of the passenger imposed on the treadle in the exit-way, as the bell-crank 341 has been operated to a 70 position in which it is free of the catch 362, and compressed air thereupon flows from the container 267 through the valve controlled by the lever 86 and pipes 282 and 432 into the left hand end of the cylinder 398 in Fig. 56, with the result of swinging the exit-door to open position, these doors remaining open so long as a passenger is on 75 the treadle in the exit-way or on the step at the exit-way. If the operator moves the lever 86 to the position last referred to before a passenger has stepped upon the treadle the entrance door engine in operating to open the entrance door shifts the bell-crank 341 to the right in Fig. 47 from beneath the catch 362, which releases this bell-crank for operation when a passenger does 80 step upon the treadle.

As soon as the exit-way step cooperating therewith is clear of passengers, the elements hereinbefore referred to, and cooperating with the mechanism operated by the treadle, return these various treadle-operated parts to normal position, whereupon the spring 419 shifts the exit-door engine valve to normal position in which position 85 compressed air is supplied to the cylinder 398 for closing the exit door. If the motorman has already returned the lever 86 to normal "release" position, which effects the 90 closing of the entrance door by operating the entrance door engine reversely to that 95 described, in which operation the shaft 325 rotates counter-clockwise in Fig. 47, the arm 342 of the lever 341, in the return of the treadle-operated parts to normal position, will force the catch 362 to the left 100 in Fig. 47 to the dotted position therein shown against the resistance of its spring 368, and will finally take the position shown in Fig. 47 in which the catch 362 extends over the roller 343. If, however, the motorman has not returned the lever 86 to "release" position before the passenger leaves the exit step, the lever 341 will assume the 105 full line position shown in Fig. 47 and extend beneath the catch 362, upon the movement of the lever to the position stated.

By providing the auxiliary lever control 87 the motorman may either so condition the mechanism controlling the exit-door that the presence of a passenger on the treadle in the exit-way will effect the opening of the exit-door, or the exit-door may be opened independently of the position of the passengers, all independently of the opening of the entrance door. Referring now particularly to Figs. 16, 17 and 18, the rotation of the auxiliary handle 87 throughout less than 90° from normal position, assuming that the lever 86 has been rotated to a position in which the brakes are applied, in which position the member 256 bears upwardly against the under sides of the lugs 251, operates to withdraw the latch 362 from a position in which it obstructs clockwise rotation of the lever 341 in Fig. 48, thus freeing this lever with the result that the weight of a passenger on the treadle at the exit-way actuates the valve of the exit-door engine to a position in which the exit-door engine operates to open the exit-door, the door thus opening whether or not the passenger was on the treadle at the time the auxiliary handle was operated or becomes positioned on the treadle after this handle is so operated. The exit-door closes as soon as the exit-way and step cooperating therewith are free of passengers, this being effected by the springs which cooperate with the treadle-actuated mechanism, it being understood that if the auxiliary handle 87 has been returned to normal position before the passengers have cleared the exit step, the arm 342 of the lever 341 will ride against the outer end of the catch 362, forcing it to the left in Fig. 47 against the action of its spring and becoming positioned thereunder as shown in this figure.

It will also be understood that the auxiliary handle 87 will return, under the action of the spring 249, to the normal position shown in Figs. 16, 17 and 18, regardless of the position occupied by the lever 86, upon the operator releasing his grasp upon the lever 87. The exit-door is caused to open solely by the act of the motorman, by actuating the lever 87 to a position in which the lugs 251 engage the recesses 253 (Fig. 18), resulting in the locking of the auxiliary handle to the position in which it is operated. Thus operating the lever 87 results in the forcing of the rod 354 downwardly to a position in which the shaft 350 is rotated to an extent sufficient to cause the valve mechanism of the exit-door-operating engine to be in a position for supplying fluid pressure to this engine for opening the exit-door, as hereinbefore explained. The exit-door remains open, regardless of the position occupied by the passengers, until the motorman returns the lever 86 to

a position in which the brakes are released 65 whereupon the auxiliary handle 87 is automatically released for automatic return, under the action of its spring, to normal position, in which movement the valve controlling the exit-door engine returns to normal position if the exit-way and step cooperating therewith are clear of passengers, whereupon compressed air enters the door-closing end of the exit-door-operating cylinder and the exit-door closes. If a passenger 70 is on the treadle or on the exit-door step when the lever 87 returns to normal position, the exit-door will remain open, until the exit-way and step are clear of passengers, whereupon the valve of the exit-door 80 engine moves to normal position and the exit-door automatically closes.

While we have illustrated and described certain embodiments of our invention, we do not wish to be understood as intending 85 to limit it thereto, as the invention may be embodied in other constructions and those shown and described may be variously modified and altered without departing from 90 the spirit of our invention.

What we claim as new; and desire to secure by Letters Patent, is:

1. A vehicle having entrance and exit-ways, and barrier means for preventing persons boarding the vehicle through said 95 exit-way operable for opening by the act of a passenger combined with an act of the operator of the vehicle and automatically returnable to barrier-forming position when the passenger leaving the vehicle reaches a 100 certain position.

2. A vehicle having entrance and exit-ways, and barrier means for preventing persons boarding the vehicle through said 105 exit-way operable for opening by the act of a passenger combined with an act of the operator of the vehicle and automatically returnable to barrier-forming position when the passenger leaving the vehicle clears the 110 exit-door step.

3. A vehicle having entrance and exit-ways, and barrier means for preventing persons boarding the vehicle through said 115 exit-way movable to open position by the act of a passenger going through said exit-way combined with an act of the operator of the vehicle and automatically returnable to barrier-forming position when the passenger leaving the vehicle reaches a certain position.

4. A vehicle having entrance and exit-ways, barrier means for preventing persons boarding the vehicle through said exit-way and controlling means operable by the operator of the vehicle, said barrier means being operable for opening by the act of a passenger combined with the actuation of 125 said controlling means and automatically

operable to barrier-forming position when the passenger leaving the vehicle reaches a certain position.

5. A vehicle having entrance and exit-ways, barrier means for preventing persons boarding the vehicle through said exit-way, and mechanism operable by the combined acts of a passenger and the operator of the vehicle, for temporarily moving said barrier means out of barrier-forming position.

6. A vehicle having entrance and exit-ways, barrier means for preventing persons boarding the vehicle through said exit-way, and mechanism involving a controlling element upon which the passenger steps in passing through the exit-way, operable by the act of a passenger stepping upon said controlling element, combined with an act of the operator of the vehicle, for moving said barrier means out of barrier-forming position.

7. A vehicle having entrance and exit-ways, barrier means for preventing persons boarding the vehicle through said exit-way, and mechanism operable by the combined acts of a passenger and the operator of the vehicle, for moving said barrier means out of barrier-forming position and automatically returnable to barrier-forming position when the passenger leaving the vehicle reaches a certain position.

8. A vehicle having entrance and exit-ways, barrier means for preventing persons boarding the vehicle through said exit-way, and controlling means operable by the operator of the vehicle, said barrier means being operable for opening by the act of a passenger combined with the actuation of said controlling means and automatically returnable to barrier-forming position when the passenger leaving the vehicle reaches a certain position, independent of the act of the operator of the vehicle.

9. A vehicle having entrance and exit-ways, barrier means for preventing persons boarding the vehicle through said exit-way, barrier means for said entrance-way, and mechanism controllable by the operator of the vehicle for controlling the opening and closing of said barrier means at the entrance-way and controlling the movement of said barrier means at the exit-way, said last-referred-to barrier means being operable for opening by the act of a passenger combined with the actuation of said mechanism.

10. A vehicle having entrance and exit-ways, barrier means for preventing persons boarding the vehicle through said exit-way, barrier means for said entrance-way mechanism controllable by the operator of the vehicle for controlling the opening and closing of said barrier means at the entrance-way and controlling the movement of said barrier means at the exit-way, said

last-referred-to barrier means being operable for opening by the act of a passenger combined with the actuation of said mechanism, and automatically returnable to barrier-forming position when the passenger leaving the vehicle reaches a certain position.

11. A vehicle having entrance and exit-ways, barrier means for preventing persons boarding the vehicle through said exit-way, barrier means for said entrance-way, and mechanism controllable by the operator of the vehicle for controlling the opening and closing of said barrier means at the entrance-way and controlling the movement of said barrier means at the exit-way, said first-referred-to barrier means being operable for opening by the act of a passenger combined with the actuation of said mechanism, said mechanism being operable to a position in which the barrier-means at the entrance-way are opened and, in combination with the act of a passenger, the barrier means at the exit-way are opened, or to a position in which the barrier means for the entrance-way remain closed and the act of a passenger, combined with the act of the operator in actuating said mechanism, effects the movement of the barrier means at the exit-way out of barrier-forming position.

12. A vehicle having entrance and exit-ways, barrier means for preventing persons boarding the vehicle through said exit-way, barrier means for said entrance-way and mechanism controllable by the operator of the vehicle for controlling the opening and closing of said barrier means at the entrance-way and controlling the movement of said barrier means at the exit-way, said first-referred-to barrier means being operable for opening by the act of a passenger combined with the actuation of said mechanism, said mechanism being operable to a position in which the barrier-means at the entrance-way are opened and, in combination with the act of a passenger, the barrier means at the exit-way are opened, or to a position in which the barrier means for the entrance-way remain closed and the act of a passenger, combined with the act of the operator in actuating said mechanism, effects the movement of the barrier means at the exit-way out of barrier-forming position, said first-named barrier means being automatically returnable to barrier-forming position when the passenger leaving the vehicle reaches a certain position.

13. A vehicle having entrance and exit-ways, barrier means for preventing persons boarding the vehicle through said exit-way, brake mechanism for the vehicle, and combined brake-controlling and barrier-means-controlling mechanism operable by the operator of the vehicle and so constructed and

arranged that said barrier means is operable for opening by the act of a passenger combined with the actuation of said last-named mechanism when the latter has been moved to a certain position in which the brakes are applied.

14. A vehicle having entrance and exit-ways, barrier means for preventing persons boarding the vehicle through said exit-way, 10 brake mechanism for the vehicle, and combined brake-controlling and barrier-means-controlling mechanism operable by the operator of the vehicle and so constructed and arranged that said barrier means is operable for opening by the act of a passenger combined with the actuation of said last-named mechanism when the latter has been moved to a certain position in which the brakes are applied, said barrier means being 20 automatically returnable to barrier-forming position when the passenger leaving the vehicle reaches a certain position.

15. A vehicle having entrance and exit-ways, barrier means for preventing persons boarding the vehicle through said exit-way, brake mechanism for the vehicle, and combined brake-controlling and barrier-means-controlling mechanism operable by the operator of the vehicle and so constructed and arranged that said barrier means is operable for opening by the act of a passenger combined with the actuation of said last-named mechanism when the latter has been moved to a certain position in which the brakes are applied, said barrier means being automatically returnable to barrier-forming position when the passenger leaving the vehicle reaches a certain position.

16. A vehicle having entrance and exit-ways, barrier means for preventing persons boarding the vehicle through said exit-way, and mechanism controlling said barrier means and momentarily movable by the combined act of a passenger going through said exit-way and an act of the operator of the vehicle.

17. A vehicle having entrance and exit-ways, barrier means for preventing persons boarding the vehicle through said exit-way, and mechanism controlling said barrier means and movable by the combined acts of a passenger going through said exit-way and an act of the operator of the vehicle and automatically returnable to barrier-forming position when the passenger leaving the vehicle reaches a certain position.

18. A vehicle having entrance and exit-ways, barrier means for preventing persons boarding the vehicle through said exit-way, and mechanism controlling said barrier means and temporarily movable by the

mere act of a passenger going through said exit-way combined with an act of the operator of the vehicle.

19. A vehicle having entrance and exit ways, barrier means for preventing persons boarding the vehicle through said exit way, and mechanism controlling said barrier means and movable by the mere act of a passenger going through said exit-way combined with an act of the operator of the vehicle and automatically returnable to barrier-forming position when the passenger leaving the vehicle reaches a certain position.

20. A vehicle having entrance and exit ways, barrier means for preventing persons boarding the vehicle through said exit way, and mechanism involving a controlling element which is engaged and actuated by the mere act of a passenger going through the exit-way, and which, combined with an act of the operator, temporarily effects the moving of the barrier means out of barrier-forming position.

21. A vehicle having entrance and exit ways, barrier means for preventing persons boarding the vehicle through said exit way, and mechanism involving a controlling element which is engaged and actuated by the mere act of a passenger going through the exit-way, and which, combined with an act of the operator, temporarily effects the moving of the barrier means out of barrier-forming position, said barrier means being automatically returnable to barrier-forming position when the passenger leaving the vehicle reaches a certain position.

22. A vehicle having entrance and exit ways, barrier means for preventing persons boarding the vehicle through said exit way, barrier means for said entrance way and mechanism controllable by the operator of the vehicle for controlling the opening and closing of said barrier means at the entrance way and controlling the movement of said barrier means at the exit-way, said last-referred-to barrier means being operable for opening by the mere act of a passenger going through the exit-way, combined with the actuation of said mechanism.

23. A vehicle having entrance and exit ways, barrier means for preventing persons boarding the vehicle through said exit-way, barrier means for said entrance way, and mechanism controllable by the operator of the vehicle for controlling the opening and closing of said barrier means at the entrance-way and controllable by the combined acts of said operator and passenger, for opening the barrier means at the exit-way.

24. A vehicle having entrance and exit ways, barrier means for preventing persons boarding the vehicle through said exit-way, brake mechanism for the vehicle, combined brake-controlling and barrier-means-control-

ling mechanism operable by the operator of the vehicle, and means cooperating with said mechanism and operable by the act of a passenger to effect the movement of said barrier means out of barrier-forming position when said mechanism has been moved to a certain position in which the brakes are applied.

25. A vehicle having entrance and exit ways, barrier means for preventing persons boarding the vehicle through said exit-way, brake mechanism for the vehicle, combined brake-controlling and barrier-means-controlling mechanism operable by the operator of the vehicle, and means cooperating with said mechanism and operable by the act of a passenger to effect the movement of said barrier means out of barrier-forming position when said mechanism has been moved to a certain position in which the brakes are applied, said barrier means being automatically returnable to barrier-forming position when the passenger leaving the vehicle reaches a certain position, independent of the position of said mechanism and automatically returnable to said position upon the releasing of the brakes irrespective of the position of the passenger.

26. A vehicle having entrance and exit ways, barrier means for preventing persons boarding the vehicle through said exit-way, brake mechanism for the vehicle, means for controlling said brake mechanism, and means controlling said barrier means, operable to permit said barrier means to be opened only after said third-named means have been moved to a position in which the said brake mechanism is actuated to brake-applied position.

27. A vehicle having entrance and exit ways, barrier means for preventing persons boarding the vehicle through said exit-way, brake mechanism for the vehicle, means for controlling said brake mechanism, and means controlling said barrier means operable to permit said barrier means to be opened only after said third-named means have been moved to a position in which the said brake mechanism is actuated to brake-applied position, and means for moving said barrier means out of barrier-forming position and involving a controlling element movable to controlling position only when said third-named means have been moved to a position in which said brake mechanism is in applied position.

28. A vehicle having entrance and exit ways, barrier means for preventing persons boarding the vehicle through said exit-way, brake mechanism for the vehicle, means for controlling said brake mechanism, and means controlling said barrier means, operable to permit said barrier means to be opened, only after said third-named means have been moved to a position in which the

said brake mechanism is actuated to brake-applied position, said last-named means and said barrier means being returnable to normal position, upon moving said third-named means to brake-release position.

29. A vehicle having entrance and exit ways, barrier means for preventing persons boarding the vehicle through said exit-way, brake mechanism for the vehicle, means for controlling said brake mechanism and means controlling said barrier means operable to permit said barrier means to be opened, only after said third-named means have been moved to a position in which the said brake mechanism is actuated to brake-applied position, and means for moving said barrier means out of barrier-forming position and involving a controlling element movable to controlling position only when said third-named means have been moved to a position in which said brake mechanism is in applied position, said last-named means and said barrier means being returnable to normal position, upon moving said third-named means to brake-release position.

30. A vehicle having entrance and exit ways barrier means for preventing persons boarding the vehicle through said exit-way, power means for actuating said barrier means, and means separately controlled by the operator of the vehicle and by a passenger and operable by the combined acts of both, for controlling the operation of said power means.

31. A vehicle having entrance and exit ways, barrier means for preventing persons boarding the vehicle through said exit-way, power means for actuating said barrier means, and means separately controlled by the operator of the vehicle and by a passenger and operable by the combined acts of both, for controlling the operation of said power means, said barrier means being returnable automatically to barrier-forming position when the passenger in leaving the vehicle reaches a certain position.

32. A vehicle having entrance and exit ways, barrier means for preventing persons boarding the vehicle through said exit-way, means for actuating said barrier means, and controlling elements for said last-named means, one of which is controlled by the position occupied by a passenger and the other of which is controlled by the operator of the vehicle, the opening of said barrier means requiring the combined acts of a passenger and the operator, said barrier means being automatically returnable to barrier-forming position when the passenger leaving the vehicle reaches a certain position, regardless of the position occupied by the one of the controlling elements actuated by the operator, and also automatically movable to barrier-forming position.

33. In a vehicle, the combination of bar-

rier means, power means for moving said barrier means, and a plurality of controlling devices one of which is operable by the operator of the vehicle and the other by a 5 passenger, for controlling said power means and operating, when both of said devices are actuated, to effect the operation of said power means for moving said barrier means.

34. In a vehicle, the combination of barrier 10 means, power means for moving said barrier means, and a plurality of controlling devices one of which is operable by the operator of the vehicle and the other by a passenger, for controlling said power means and operating, when both of said devices are actuated, to effect the operation of said power means for moving said barrier means, said barrier means being automatically returnable to normal position 15 when operation of the one of said controlling devices which is operable by the passenger, is discontinued.

35. In a vehicle, the combination of barrier 20 means, power means for moving said barrier means, and a plurality of controlling devices one of which is operable by the operator of the vehicle and the other by a passenger, for controlling said power means and operating, when both of said devices 25 are actuated, to effect the operation of said power means for moving said barrier means, said power means operating to return said barrier means to normal position when operation of the one of said controlling devices operable by the passenger, is discontinued.

36. In a vehicle, the combination of its 30 platform containing entrance and exit ways, barrier means at said ways, a plurality of power devices for actuating said barrier means, a controlling device operable by the operator of the car for controlling the supplying of power to said power devices, and a controlling element cooperating with said 35 power control in the controlling of the supplying of power to the power device which controls said barrier means at the exit-way whereby the movement of said last-referred-to barrier means to open position 40 may not be effected by said controlling element alone but only in combination with the power-supply means operable by the operator of the vehicle.

37. In a vehicle having entrance and exit 45 ways, barrier means for preventing persons boarding the vehicle through said exit-way, and mechanism including an actuating member which is moved by a passenger in the movement of the passenger through the 50 exit-way, and an actuating member which is actuated by the operator of the vehicle, operating to temporarily move said barrier means out of barrier-forming position.

38. In a vehicle having entrance and exit 55 ways, barrier means for preventing persons

boarding the vehicle through said exit-way, and mechanism including an actuating member which is moved by a passenger in the movement of the passenger through the exit-way, and an actuating member which is actuated by the operator of the vehicle, operating to move said barrier means out of barrier-forming position and automatically 70 return the latter to barrier-forming position.

39. A vehicle having entrance and exit 75 ways, barrier means for preventing persons boarding the vehicle through said exit-way, a fluid-pressure-operated device operating to move said barrier means out of barrier-forming position, and mechanism operated 80 by the act of a passenger leaving the vehicle through said exit-way combined with an act of the operator of the vehicle for controlling operation of said device.

40. A vehicle having entrance and exit 85 ways, barrier means for preventing persons boarding the vehicle through said exit-way, a fluid-pressure-operated device operating to move said barrier means out of barrier-forming position, and mechanism operated 90 by the act of a passenger leaving the vehicle through said exit-way combined with an act of the operator of the vehicle for controlling operation of said device, said barrier means being automatically return- 95 able to barrier-forming position.

41. In a vehicle having entrance and exit 100 ways, the combination of barrier means at the exit-way, a movable step at the exit way, means whereby said barrier means and step are connected together for simultaneous operation, said barrier means being operable out of barrier-forming position, and means whereby said barrier-forming means are maintained out of barrier-forming position by the act of a passenger while he goes through the exit way and over said step.

42. In a vehicle having entrance and exit 105 ways, the combination of barrier means at the exit way, a movable step at the exit way, means whereby said barrier means and step are connected together for simultaneous operation, said barrier means being operable out of barrier-forming position by the act of a passenger in the exit way combined with an act of the operator of the vehicle, said barrier means being automatically returnable to barrier-forming position 110 after the passenger has cleared the exit way and said step.

43. In a vehicle, the combination of entrance and exit ways, barrier means in said exit way, an actuating element positioned to be engaged by a passenger in passing through the exit way, a power device for actuating said barrier means, valve mechanism controlling the supplying of power to said power device, controlling mechanism operable by the operator of the vehicle, and means for controlling said valve mechanism 115 120 125 130

operable by the combined actuations of said passenger-operated controlling element and said control mechanism.

44. In a vehicle, the combination of entrance and exit ways, barrier means at the exit-way, a power device for actuating said barrier means, means controlling the supplying of power to said device, and a plurality of means respectively operated by a passenger in the exit way and by the operator of the vehicle, for actuating by their joint operation, said last-named means to direct power to said power device.

45. In a vehicle, the combination of entrance and exit ways, barrier means at the exit-way, a power device for actuating said barrier means, means controlling the supplying of power to said device, and involving a movable element, a tilttable and rotatable shaft operating when rotated to control the position of said movable element, and a plurality of means one operating, when actuated, to rock when the latter is tilted in one direction and the other to tilt said shaft in said direction, said plurality of means being operable, respectively, by the act of a passenger and by an act of the operator.

46. A vehicle having entrance and exit ways, barrier means for preventing persons boarding the vehicle through said exit-way, barrier means for said entrance way, and mechanism controllable by the operator of the vehicle for controlling the opening and closing of said barrier means at the entrance-way and controllable by the combined acts of said operator and passenger, for opening the barrier means at the exit-way, and operable to close said barrier means at the exit-way automatically by the passenger moving to a certain position or by the act of the operator.

47. In a vehicle, the combination with its platform having an exit-way and a barrier-forming means for said exit-way, of means controlling the movement of said barrier-forming means including a treadle located in said exit-way, to be stepped upon by passengers passing through said exit-way, said treadle having an extension at which it is pivoted at a point laterally beyond the marginal edges of the body of the treadle, to adapt it to move relative to the platform.

48. In a vehicle, the combination with its platform having an exit-way and a barrier-forming means for said exit-way, of means controlling the movement of said barrier-forming means including a treadle located in said exit-way, to be stepped upon by passengers passing through said exit-way, said treadle having arms rigid with its body portion which extend beneath said platform at an edge of said opening, said arms being pivoted to said platform at their outer ends.

49. In a vehicle, the combination of en-

trance and exit ways, barrier means at the exit-way, a power device for actuating said barrier means, means controlling the supplying of power to said device and involving a movable element, a tilttable and rotatable shaft operating when rotated to control the position of said movable element, means operable to cause said shaft to rotate when tilted, and means operable for tilting said shaft, the latter in such movement rotating.

50. In a vehicle, the combination of entrance and exit ways, barrier means at the exit way, a power device for actuating said barrier means, means controlling the supplying of power to said device and involving a movable element, a tilttable and rotatable shaft operating when rotated to control the position of said movable element, said shaft being provided with a laterally-extending arm, a stop member adapted to be engaged by said arm for causing said shaft to rotate when the latter is tilted, said stop member being normally out of a position in which it is engaged by said arm and movable into a position in which it is engaged by said arm, and means for tilting said shaft.

51. In a vehicle, the combination of entrance and exit ways, barrier means at the exit way, a power device for actuating said barrier means, means controlling the supplying of power to said device and involving a movable element, a tilttable and rotatable shaft operating when rotated to control the position of said movable element, means movable into and out of a position in which said shaft is rotated when tilted, a lever operatively engaging said shaft and relative to which said shaft is rotatable, operating when actuated to tilt said shaft, and means for actuating said lever.

52. In a vehicle having entrance and exit ways, the combination of barrier means for preventing persons boarding the vehicle through said exit-way operable for opening by the act of a passenger combined with an act of the operator of the vehicle, and supplementary means controllable by said operator alone for effecting the movement of said barrier means out of barrier-forming position.

53. A vehicle having entrance and exit ways, barrier means for said exit-way, brake mechanism for the vehicle, combined brake-controlling and barrier-means-controlling mechanism operable by the operator of the vehicle and so constructed and arranged that said barrier means is operable for opening by the act of a passenger combined with the actuation of said last-named mechanism when the latter has been moved to a certain position in which the brakes are applied, and supplementary means, operated by the operator alone, for moving said barrier means out of barrier-forming position.

54. A vehicle having entrance and exit

ways, barrier means for preventing persons boarding the vehicle through said exit-way, a power device for actuating said barrier means, means operable by the act of a passenger combined with an act of the operator of the vehicle for actuating said power device to move said barrier means, and means operated by said operator alone for effecting the operation of said power device to move said barrier means.

55. A vehicle having entrance and exit ways, barrier means for preventing persons boarding the vehicle through said exit-way, brake mechanism for the vehicle, a power device operating, when actuated, to move said barrier means out of barrier-forming position, combined brake-controlling and power-device-controlling mechanism operable by the operator of the vehicle and so constructed and arranged that said power device is caused to actuate by the act of a passenger combined with the actuation of said last-named mechanism when the latter has been moved to a certain position in which the brakes are applied, and means operated by said operator alone for effecting the operation of said power device for causing said barrier means to move out of barrier-forming position.

56. In a vehicle, the combination of entrance and exit ways, barrier means at the exit-way, a power device for actuating said barrier means, means controlling the supplying of power to said device and involving a movable element, a tilttable and rotatable shaft operating when rotated to control the position of said movable element, mechanism operating, when actuated, to cause said shaft to rotate when tilted, means for tilting said shaft and means operated by the operator alone for rotating said shaft to control the position of said movable element.

57. In a vehicle, the combination of entrance and exit ways, barrier means at the exit-way, a power device for actuating said barrier means, means controlling the supplying of power to said device and involving a movable element, a tilttable and rotatable shaft operating when rotated to control the position of said movable element, a stop member cooperating with said shaft and movable into a position in which it causes said shaft to rotate when the latter is tilted, means for tilting said shaft, a rotatable member adapted to be rotated by the act of the operator alone, and mechanism operatively connected with said rotatable member and with said shaft for rotating the latter.

58. A vehicle having entrance and exit ways, barrier means for preventing persons boarding the vehicle through said exit ways, means controlling the position of said barrier means and involving a tilttable and ro-

tatable shaft operating when rotated to control the movement of said barrier means, a rod mounted to move up and down on the vehicle, means on said rod, operating when said rod is in a certain position, to cause said shaft to rotate when the latter is tilted, and means operatively engaging said shaft for tilting the latter.

59. A vehicle having entrance and exit ways, barrier means for preventing persons boarding the vehicle through said exit ways, means controlling the position of said barrier means and involving a tilttable and rotatable shaft operating when rotated to control the movement of said barrier means, a rod mounted to move up and down on the vehicle, means on said rod, operating when said rod is in a certain position, to cause said shaft to rotate when the latter is tilted, means operatively engaging said shaft for tilting the latter, means for rotating said rod, and means operatively connecting said rod with said shaft and operating to rotate said shaft when said rod is rotated.

60. A vehicle having entrance and exit ways, barrier means for preventing persons boarding the vehicle through said exit way, a rotatable and tilttable shaft operating when rotated to control the position of said barrier means, said shaft being provided with laterally-extending arms, a rod mounted on said vehicle to be movable up and down thereon and rotated and provided with a stop surface adapted when said rod is moved lengthwise to one position to engage one of said arms and effect the rotating of said shaft when the latter is tilted, means operatively engaging said shaft for tilting the latter, and means operatively engaging said rod and the other of said arms for rocking said shaft when said rod is rotated.

61. A vehicle having entrance and exit ways, barrier means for preventing persons boarding the vehicle through said exit way, means controlling the movement of said barrier means and involving a controlling element, mechanism controlling said element, operable by the combined acts of the operator of the vehicle and an act of a passenger, and mechanism operated by said operator alone, for controlling said element.

62. A vehicle having entrance and exit ways, barrier means for preventing persons boarding the vehicle through said exit way, mechanism operable by the act of a passenger combined with an act of the operator of the vehicle for controlling said barrier means, auxiliary means operable by said operator for actuating said barrier means, and means interlocking said auxiliary means against actuation until said mechanism has been moved into a certain position.

63. A vehicle having entrance and exit

ways, barrier means for preventing persons boarding the vehicle through said exit way, brake mechanism for the vehicle, combined brake-controlling and barrier-means-controlling mechanism operable by the operator of a vehicle and so constructed and arranged that said barrier means are operable for opening by the act of a passenger combined with the actuation of said last-named mechanism when the latter has been moved to a certain position, auxiliary means operable by said operator for controlling the position of said barrier means, and means for preventing the operation of said auxiliary means until said second-named mechanism has been moved to a position in which said brake mechanism operates to brake the vehicle.

64. A vehicle having entrance and exit ways, barrier means for preventing persons boarding the vehicle through said exit way, brake mechanism for the vehicle, combined brake-controlling and barrier-means-controlling mechanism operable by the operator of a vehicle and so constructed and arranged that said barrier means are operable for opening by the act of a passenger combined with the actuation of said last-named mechanism when the latter has been moved to a position in which said brakes are applied, auxiliary means operable by said operator for controlling the position of said barrier means, and means for preventing the operation of said auxiliary means until said second-named mechanism has been moved to a position in which said brake mechanism operates to brake the vehicle.

65. A vehicle having entrance and exit ways, barrier means for preventing persons boarding the vehicle through said exit way, brake mechanism for the vehicle, combined brake-controlling and barrier-means-controlling mechanism operable by the operator of a vehicle and so constructed and arranged that said barrier means are operable for opening by the act of a passenger combined with the actuation of said last-named mechanism when the latter has been moved to a certain position, auxiliary means operable by said operator for controlling the position of said barrier means, and means locking said auxiliary means in the position to which it is operated as stated and releasable in the movement of said second-named mechanism to a given position, said auxiliary means when released returning to normal position.

66. A vehicle having entrance and exit

ways, barrier means for preventing persons boarding the vehicle through said exit way, brake mechanism for the vehicle, combined brake-controlling and barrier-means-controlling mechanism operable by the operator of a vehicle and so constructed and arranged that said barrier means are operable for opening by the act of a passenger combined with the actuation of said last-named mechanism when the latter has been moved to a position in which said brake mechanism brakes the vehicle, auxiliary means operable by said operator for controlling the position of said barrier means, said auxiliary means being automatically returnable to normal position, means locking said auxiliary means against actuation until said brake mechanism has been applied, and releasable means for holding said auxiliary means in the position to which it is actuated as stated until said brakes are released.

67. A vehicle having entrance and exit ways, barrier means for preventing persons boarding the vehicle through said exit way, brake mechanism for the vehicle, brake-controlling and barrier-means-controlling mechanism operated by the operator of the vehicle and through the medium of which, combined with an act of the passenger, said barrier means are actuated, said brake mechanism involving means whereby an emergency application of the brakes may be effected, and means operating automatically, upon an emergency-brake application, to render said barrier means non-obstructive to the passage of passengers outwardly through said exit-way.

68. A vehicle having entrance and exit ways, barrier means for preventing persons boarding the vehicle through said exit-way, fluid-pressure-means for actuating said barrier means and operating, by the force of fluid-pressure, to hold said barrier means in barrier-forming position, brake mechanism for the vehicle, combined brake-controlling and barrier-means-controlling mechanism actuated by the operator of the vehicle for controlling said fluid-pressure mechanism and operating, in combination with an act of a passenger, to move said barrier means, said mechanism involving means whereby an emergency brake application may be effected, and means whereby an emergency-brake application automatically releases the fluid pressure holding said barrier means in closed position.
